UNITED STATES PATENT OFFICE.

CLARENCE E. BEACH, OF BINGHAMTON, NEW YORK, ASSIGNOR TO THE GAMEWELL COMPANY, OF NEWTON, MASSACHUSETTS, A CORPORATION OF MASSACHUSETTS.

SIGNALING SYSTEM.

Application filed December 7, 1920. Serial No. 428,969.

To all whom it may concern:

Be it known that I, CLARENCE E. BEACH, a citizen of the United States, residing at Binghamton, county of Broome, and State 5 of New York, have invented certain new and useful Improvements in Signaling Systems, of which the following is a specification.

This invention relates to signaling systems comprising a plurality of signal initiating stations and signal responsive devices, and is particularly adapted for use in signaling systems having a plurality of code signal initiating stations and signal responsive devices, some of which devices are responsive to all of the initiating stations, and other of which devices are responsive to only a certain one or more initiating stations. Such responsive devices as are responsive 10 to all initiating stations will be hereinafter referred to as "general responsive devices," and those responsive to only certain initiating stations will be hereinafter referred to as "local responsive devices."

25 Signaling systems of certain types (such as, for example, automatic fire alarm systems) ordinarily stand unused for long periods; and, on the other hand, several initiating stations of any such systems are likely 30 to be called upon concurrently, when abnormal or dangerous conditions develop. When such systems are employed for the purpose of summoning assistance, it is of prime importance that code signals shall be 35 intelligently manifested with utmost dispatch to those whose assistance is to be summoned, even when a plurality of initiating stations are concurrently subjected to influences calculated to cause them to transmit 40 their respective code signals.

It is ordinarily deemed essential that all line wires and terminals of such systems shall, while in normal condition, be subjected to a continuous electrical test; such systems should, therefore, be of the "closed circuit type"; however, it is deemed undesirable, (and, in many instances, incurs a cost of upkeep which is deemed prohibitive) to maintain a current flow, throughout 45 long periods of non-use, as great as that which should be utilized during the activity of initiating stations. It is also well recognized that the use of independent current sources at the scattered locations of the 50 initiating stations is undesirable from con-

siderations of cost of installation and maintenance, and of dependability of operation.

In various types of automatic alarm service, suitably operable circuit adjusters are associated with transmitting mechanisms at 60 various initiating stations so that, upon predetermined operation of any one of such adjusters, the associated transmitting mechanism will be caused to act. In the use of such systems it has been found that, under certain circumstances, conditions may arise under which such adjusters will be operated momentarily or for a comparatively short period, and that under other circumstances such adjusters will be maintained in 65 operated condition for a comparatively long period. It is desirable that, under all circumstances, each signal shall be so transmitted as to indicate, by means of a suitable code, the station from which it originated; 70 and it is further desirable that, when any adjuster is maintained in operated condition for a comparatively long period, the resultant code signal will distinctively differ from that which will result from operation of an adjuster for a period of comparatively brief duration. In some cases, 75 it is desirable that code signals representing the operation of an adjuster for a comparatively long period shall be manifested by all 80 general responsive devices and by a local responsive device associated with the active initiating station, and that signals resulting from the operation of an adjuster for a comparatively short period shall not cause 85 manifestation by certain general responsive devices. For example, in large institutions such as department stores and hospitals, it is desirable to provide signaling systems operable in the event of fire or other emergency 90 for summoning assistance and for warning the occupants in case of extreme emergency, but it is highly undesirable to alarm the occupants upon the occurrence of any minor emergency involving the development, for 95 a comparatively short period, of some condition (such as a rapid rise of temperature) even if same would constitute a very definite hazard if continued for a longer period. On the other hand, those in authority should be 100 summoned to investigate and guard against the recurrence of even such minor emergencies.

It is obvious that signals should be given the right of way in the order of their im- 110

portance; and that, to this end, the clear manifestation, in an orderly sequence, of signals representing the operation of adjusters for periods of comparatively long duration should be assured, when adjusters are concurrently operated for periods of varying duration.

An object of this invention is to provide a system having transmitting mechanism whereby signals of a certain predetermined class will be given precedence over signals of any other class or classes, to the end that signals of less importance than those of such preferred class will invariably give way to those of such preferred class; complete non-interference being assured between different signals of such preferred class.

A further object of this invention is to provide, in a system having transmitting mechanism at initiating stations operable to transmit two classes of signals, means whereby signals of one of such classes will cause response of all general responsive devices and whereby signals of the other of such classes will cause response of only a predetermined one or more of such general responsive devices.

A further object of this invention is to provide means at initiating stations of such a system whereby a desired number of repetitions of signals of one of said classes will be assured, after the transmission thereof has progressed beyond a certain point, regardless of the continuance of the period during which the adjuster of such a station is maintained in the operated condition intended to cause the transmission of such signals.

A further object of this invention is to provide mechanism at initiating stations of such a system whereby signals of one of the classes which are transmitted by any or certain ones of such initiating stations will cause manifestation thereof by respective local responsive devices.

A further object of this invention is to provide such a system in which the line conductors will be under constant test at a current strength substantially less than that of impulses incident to the transmission of one class of signals.

Another object is to provide construction and arrangement of parts whereby a common or centralized current source will act, through the line wires provided for the transmission of intended code signals, to energize tripping magnets of widely scattered transmitting mechanisms in response to the operation of circuit adjusters associated respectively therewith.

Still further objects, together with their inherent advantages, will be in part obvious and in part hereinafter specifically set forth.

The features of this invention may be variously combined, in groups having all

or less than all of said features, to meet diverse service conditions and requirements. In constructing a signaling system in accordance with all of the features of this invention:—

A signal circuit is provided which comprises two parallel conductor loops, each of which passes through or communicates with each of a plurality of signal initiating stations; a current source is connected between one end of one loop and the opposite end of the other loop; a connection of comparatively high resistance is provided between the remaining ends of said loops; and two classes of general responsive devices and a plurality of local responsive devices are suitably connected for desired response to said circuit.

One class of said general responsive devices is arranged to suitably manifest circuit interruptions occurring at any point in either of said loops, the other class of said general responsive devices is arranged for response to current flow increases such as would result from interconnecting the circuit loops at any initiating station; and the local responsive devices are included in normally ineffective interconnections at various initiating stations.

As a matter of convenience, general responsive devices arranged so that they will manifest any circuit interruptions which occur at any point in either of the circuit loops, while the system is in normal inactive condition, will be hereinafter referred to as "primary responsive devices"; and general responsive devices arranged to manifest current flow increases, such as result from the establishment of an interconnection of comparatively low resistance at any initiating station, will be hereinafter referred to as "secondary responsive devices".

In cases when conditions are such that the primary responsive device should act with maximum dependability in serving both as a means of manifesting signals and as a means of giving warning in the event of impairment or rupture of the signal circuit, the electromagnet winding of such device should constitute part or all of the high resistance connection hereinbefore referred to. In cases when conditions are not such that it is deemed important that the primary responsive device should act with maximum dependability in the event of impairment or rupture of the signal circuit, such primary device winding may be connected at any point in the normal current path of the system. In any event the primary responsive device should be so arranged that it will be responsive to current flow from the current source through the normal current path including the high resistance connection; and, when such winding consists or forms part of said high resistance connec-

tion, such winding may be of much higher resistance than when connected elsewhere in the normal current path of the system.

- The electromagnet winding of the secondary responsive device should be so connected in the system that the excitation thereof will be increased in the event that the high resistance connection is shunted, as by the interconnection at any initiating station. To this end,—the winding of said secondary device should be included between one terminal or the other of the current source and the nearest initiating station connected therewith; or, if connected between any two initiating stations, such winding should be divided, part being included in one circuit loop and the remainder in the other circuit loop.

The secondary responsive device should be so arranged that it will not act in response to current flow from the source through the high resistance connection, and so that said device will act in response to current flow from said source such as will result from the establishment of an interconnection of comparatively low resistance at any one of the initiating stations.

The term "circuit loops" as herein used, is employed in a broad sense, and is not intended to necessarily imply a limitation to correspondingly or symmetrically disposed conductors; in view, however, of the fact that it is desirable to assure reasonably uniform current flow through the interconnections of all initiating stations, it is apparent that in cases where the conductor resistance between initiating stations is comparatively great,—one of such loops shall provide a current path from one terminal of the source, through the initiating stations in desired sequence, to one terminal of the high resistance connection; and that the other loop shall provide a current path from the other terminal of said source, through the initiating stations in reverse sequence, to the other terminal of said connection; thus assuring substantial uniformity of the conductor lengths of the current paths established during the effectiveness of interconnections at the various initiating stations.

At each initiating station, means is provided for formulating a code signal by alternately interrupting and establishing current flow in one or the other of the circuit loops or current paths thereat; said means comprising contacts serially included in one or the other of such current paths and operating means therefor.

Releasing means is provided for said formulating means,—such releasing means being variably operable to cause the formulation of the code signal a greater or less number of times.

An electromagnet is provided for the actuation of such releasing means, said mag-

net being so connected to one of said circuit loops, through a suitable branch path, as to be normally de-energized.

A circuit adjuster responsive to external influences is arranged to suitably control said magnet, so that,—when the signaling system is in normal condition,—such circuit adjuster may act to cause effective energization of said magnet.

For the purpose of minimizing the expenditure of electrical energy employed for the maintenance of normal current flow in the system, such branch magnet paths should be normally open, and subject to closure by associated circuit adjusters to establish an interconnection between the respective loops; such magnet connections being of sufficient resistance so that the current flow from the source during the effective energization of any one of them will be insufficient to cause response of the secondary device.

Circuit controlling means, moved by and during the operation of said formulating means, is provided for suitably governing the effectiveness of such branch magnet path. Such controlling means being periodically actuated to interrupt said branch path, regardless of the actuation of the externally influenced circuit adjuster, during circuit breaks incident to each formulation of the code signal; and to permit closure of said branch path by said adjuster after the completion of each formulation of said signal. Said controlling means being also progressively actuated during uninterrupted operation of said formulating means, to the end that, after said means has acted to formulate said code signal a predetermined one or more times, the effective energization of the magnet will be accomplished, after each formulation of the code signal, regardless of the continuity of the action of the circuit adjuster in response to the influences to which it is subjected; and, to the further end that, after said means has acted to formulate such code signal a predetermined additional one or more times, further effective energization of said magnet will be prevented.

The progressive actuation of said circuit controlling means is so accomplished that the intermittent transmission of the code signal will not alter the responsiveness of said magnet to said circuit adjuster, even if such signal is transmitted such one or more times as would alter such responsiveness if occurring uninterruptedly. Thus, should the circuit adjuster be subjected to influences causing it to repeatedly act for comparatively brief periods, the resulting intermittent actuation of the formulating mechanism will not cumulatively effect the progressively operated functions of the circuit controlling means.

Mechanical holding means is moved by the actuation of the formulating mechanism to retain the releasing means in operated position during the circuit breaks and closures incident to the formulation of the code signal, and throughout all periods when the magnet branch current path is interrupted by the periodical actuation of the circuit controlling means. The joint action of said holding means and the periodic action of the circuit controlling means therefore provide a recurrent cycle in the action of said formulating means, so governed by the electromagnet that such cycle will be repeated a greater or less number of times as determined by the effectiveness of said magnet at the conclusion of each cycle.

As previously pointed out,—normally in effective interconnections are provided at the various initiating stations, associated responsive devices being included in such interconnections. The circuit controlling means at the various initiating stations are arranged to so govern the effectiveness of the interconnections thereat that, whenever the formulating mechanism of any station has uninterruptedly accomplished a predetermined cycle of action, the interconnection at such station will be rendered effective throughout circuit closures incident to subsequent formulations of the code signal of such station. Thus, should the circuit adjuster of any station be subjected to influences causing it to repeatedly act for comparatively brief periods,—the consequent intermittent actuation of the formulating mechanism of such station will result in the formulation of circuit breaks and closures of corresponding repetitions of the code signal of such station, without such action of the circuit controlling mechanism of such station as would render effective the interconnection thereat; but should such formulating mechanism uninterruptedly act throughout a predetermined number of such code signal cycles,—such interconnection will be effective during succeeding code signal formulating closures, to the end that the secondary device and the associated local device will act in response thereto.

Means are provided at each of the initiating stations for facilitating manual restoration to normal position of the progressively actuated circuit controlling means thereat, whenever such circuit controlling means of any station has been moved by the actuation of the formulating mechanism thereat to render the electromagnet of such station unresponsive to the circuit adjuster associated therewith.

In the interests of clearness and briefness of description,—singular nouns are herein employed in reference to the circuit adjusters and the local responsive devices of

individual initiating stations, and in separately referring to either the primary or the secondary responsive devices; but it should be understood that the electromagnet of any station may be readily connected for response to any desired number of circuit adjusters, and that either one or more devices may be provided for either primary or secondary response or associated with any station. In view of the foregoing, each such herein contained reference to such adjusters or devices should be understood to signify either a singular or plural number, as circumstances might require, as fully and as clearly as if such references were, in each instance, so expanded as to read ". . . adjuster or adjusters" or ". . . device or devices" as the case might be.

For the purpose of giving precedence to secondary signals; i. e., those in response to which the secondary device should act; and for the further purpose of preventing manifestation of such secondary signals by the primary device;—the circuit controllers of the various initiating stations are so arranged that when the controller of any station acts to render the interconnection effective thereat, such controller will also interrupt the portions of both of the parallel conductor loops which extend from that station to the comparatively high resistance connection which includes the primary device.

For the purpose of preventing interruption or mutilation of any signal to which secondary and local devices should be responsive, each transmitter is so arranged and connected that two or more of the transmitters of any one circuit will not simultaneously or concurrently establish their respective interconnections, and so that, when any transmitter has acted to establish its interconnection, the magnets of all other transmitters in the same circuit will be and remain de-energized until the completion of the intended number of rounds of the signal of the station whose transmitter has so acted. Such arrangement and connection is accomplished by including the code signaling contacts of all of the transmitters in a predetermined one of the signal circuit loops; so that the breaking of such loop by the code signaling contacts of any station will prevent current flow through the electromagnet of any other station, unless such other station is connected in the loop so broken between such break and the current source. When so connected, the electromagnets of stations connected to portions of such broken loop other than toward the current source from such break can be energized only during the closed circuit periods incident to the running of the code signal formulating means of any operating station.

The arrangement of the formulating mechanisms of the various stations is such that the progressively actuated circuit controlling means forming part thereof will act 5 to render the interconnection associated therewith effective only at the expiration of a test period longer than the longest closure incident to the transmission of any code signal, throughout which test period 10 the electromagnet of such station remains energized.

Because of the duration of such test period, it is evident that if the formulating mechanism of a plurality of initiating stations start concurrently, interconnection between the circuit loops will be rendered effective only at the operating station which is connected to said loop at such point that the energization of the electromagnet thereof 20 will not be dependent upon the closure of the code signaling contacts of any of the other of such concurrently operating stations.

If it is desired that the primary device 25 should be responsive to all signals, such device should be connected in the portion of one loop or the other which extends from a terminal of the current source to the nearest initiating station; or, if such device is 30 connected between any two initiating stations, the electromagnet winding of such device should be arranged in two parts, one part of such winding being connected in one loop and the other part of such winding 35 being connected in the other loop.

If the interconnections of some initiating stations have local responsive devices connected therein, and those of other stations do not include such devices, it will be desirable 40 to include resistances in the interconnections not having such devices therein (so as to prevent excessive current flow during the effectiveness of such interconnections) unless the resistance of the circuit conductors and 45 general responsive device windings of the current path from the source through such interconnections is sufficient to prevent objectionable excessive current flow.

When the controlling electromagnets are 50 not needed at initiating stations, as, for example, would be the case when the releasing means thereat is intended for direct manual actuation thereof, the electromagnets, magnet branch current paths and controlling mechanism therefor may be omitted 55 from such stations.

If but one class of responsive devices are required, and electromagnets are not employed for the control of formulating mechanism at initiating stations, the loop ends which otherwise should be connected through a comparatively high resistance may be connected without such resistance. It is evident that, when such high resistance connection is 65 omitted, the normal current flow will be

practically as great as that incident to signaling impulses.

When systems are so arranged that the normal current flow is as great as that incident to any signaling impulses, the windings of the controlling electromagnets of initiating stations may be serially included in one loop or the other of the signal circuit. Such directly included magnet windings being controlled by circuit adjusters which, if of the normally closed type, may be arranged to short-circuit the winding at all times except when it is desired to cause effective energization of the electromagnet; and if such circuit adjusters are of the normally open type, a differential electromagnet winding should be provided, the adjusters being arranged so as to short-circuit one of the windings of the associated magnet when actuation of the formulating mechanism is desired. The introduction into a signal circuit of a large number of such differentially wound magnets will be found to produce excessive circuit resistance, but a comparatively small number of such windings can be advantageously employed in many instances.

When series connected controlling electromagnets are employed, the arrangement of the circuit controlling means of the transmitting mechanism is correspondingly altered. When normally shunted windings are employed, the periodical actuation of the circuit controlling means may be arranged to short-circuit such windings during circuit closures incident to the formulation of the code signal, if general circuit conditions are such as to render such short-circuiting necessary or desirable. The progressive actuation of the circuit controlling means associated with such series connected electromagnet windings should be arranged so that, after the formulating means has acted to transmit a predetermined signal one or more times, the circuit adjuster current path will be broken if normally closed circuit adjusters are employed, and such current path will be short-circuited if normally open circuit adjusters are employed; to the end that the effective energization of the magnet 100 will be accomplished after each succeeding formulation of the code signal regardless of the continuity of action of the circuit adjuster in response to the influences to which it is subjected. The circuit controlling means associated with such series connected windings should further be so arranged that, after an additional one or more formulations of the code signal, such electromagnet winding will be short-circuited so as to prevent further effective energization of the magnet.

Other re-arrangements and applications of the various features of this invention will readily suggest themselves to those skilled in this art.

Fig. 4 is a schematic representation similar to Fig. 3, illustrating an alternative arrangement of the primary responsive device, and repeatedly indicating similar parts for like reason;

Figs. 5 and 6 are schematic representations of circuit arrangements utilizing certain features of applicant's invention, certain parts being repeatedly indicated by Fig. 5, for like reason.

Fig. 7 is another view of the transmitter shown in Fig. 2.

Referring to Fig. 1:—the initiating stations N and N' are included in a signal circuit in which the primary responsive device P, the secondary responsive mechanism S, and the current source or battery B are serially connected.

It will be noted that the signal circuit comprises two parallel loops each extending between the current source B and the primary responsive device P, through which opposite ends of said loops are interconnected.

Each initiating station is provided with signal transmitting mechanism comprising the circuit connections inclosed by dotted line rectangles in Fig. 1, and suitable operating mechanism therefor certain details of which are more fully illustrated by Fig. 2.

Each transmitter is provided with line conductor terminals 31, 32, 33, 34, 35, 36 and 37; a controlling magnet 38; periodical-
ly actuated circuit controlling means comprising the cooperating contacts 39, 40 and 41 together with the operating arm 42 therefor; progressively actuated circuit controlling means comprising contacts 43, 44, 45, 46, 47, 48, 49 and 50 together with the operating cam 51 therefor; and code signal formulating means comprising the contacts 52 and 53 and the code wheel 54 cooperating therewith. The transmitter line conductor terminals are grouped in pairs as follows: terminals 31 and 32 are provided for the conductors communicating with the associated local responsive device L; terminals 33 and 34 are provided for receiving an end of one of the circuit loops leading to the current source and an end of the other said

current loops leading to the high resistance connection, respectively; the terminals 35 and 36 are provided for the remaining ends of said circuit loops, although one of said circuit loops may be completed through the terminal 37 instead of the terminal 36, during the closure of the contacts of any of the circuit adjusters C, C, C. The conductor 55 connects the terminal 31 and the contact 41. The conductor 56 connects the terminal 32 and the contact 45. The conductor 57 connects the terminal 33 and the contact 44. The terminal 34 is connected to contacts 39 and 47 through conductors 58, 59 and 60. The terminal 35 is connected to the contact 46 through conductor 61. The terminal 36 is connected to contacts 48 and 52 through conductors 62, 63 and 64. The terminal 37 is connected to contact 49 through conductor 65. The winding of the controlling elec- 85
tromagnet 38 is serially connected between contact 40 and contact 50 through conductors 66 and 67. Conductor 68 connects contacts 43 and 53.

As shown, the various parts of the transmitters are in their respective normal positions, the contact 39 being held in engagement with the contact 40 and away from the contact 41, by means of the arm 42; the contact 52 being held in engagement with the contact 53 by the code wheel 54; the contact 43 being permitted by the cam 51 to move into engagement with the contact 44 and away from the contact 45, said contact 45 being thus permitted to move into engagement with contacts 46 and 47; the contact 48 is permitted by the cam 51 to move away from the contact 49, and the contact 50 is likewise permitted to move into engagement with said contact 49.

While the various parts are in their respective normal positions, as thus indicated, two normally closed independent current paths are provided between respective terminals of two of the pairs of transmitter contacts. One of said paths extending from terminal 33, through conductor 57, contacts 44 and 43, conductor 68, code signal formulating contacts 53 and 52, conductors 64 and 62 to terminal 36. The other of said paths extends from terminal 34, through conductors 58 and 60, through contacts 47, 45 and 46, and through conductor 61 to terminal 35.

A local responsive device L is associated with the initiating station N; said device being represented as a bell, one terminal of which is connected through conductor 69 to transmitter terminal 31, and the other terminal of which is connected through conductor 70 to transmitter terminal 32. Circuit adjusting means comprising the circuit closers C, C, C are associated with the initiating station N, one terminal of each of said circuit closers being connected through the conductor 71 to the transmitter terminal 130

37, and the other terminal of each of said circuit closers being connected to conductor 121.

The initiating station N' comprises terminals, contacts, contact operating means, a controlling electromagnet and conductors connecting said parts, all of which are similar to those provided at the initiating station N, and hereinbefore more fully described; except that the code wheel 54 of station N' is arranged to formulate a signal differing from that for which the code wheel 54 of station N is arranged. The local responsive device L' and the circuit closers 15 C', C', and C' are associated with and connected to the initiating station N', in a manner similar to that hereinbefore more fully described in connection with the local responsive device L and the circuit closers 20 C, C, C respectively.

The primary responsive device P comprises a relay having an electromagnet 81, the armature 82 of which is normally held in engagement with the front stop 83 associated therewith, said armature being arranged to move into engagement with the back stop 84 upon de-energization of the electromagnet 81.

The electromagnet 81 is wound to a comparatively high resistance, and the resistance of such winding may be supplemented, as by the resistor R, under certain circumstances which will be hereinafter more fully set forth.

35 The battery 85 is connected between one terminal of the bell 86 and the armature 82, and the other terminal of the bell 86 is connected to the back stop 84, so that, whenever said armature 82 moves to its retracted position, a current path including the battery 85 and the bell 86 will be established; thus causing said bell to sound so long as said armature remains in retracted position.

40 The secondary responsive device S comprises an electromagnet 91, the armature 92 of which normally rests against the back stop 93 associated therewith; said armature being arranged to act in response to predetermined energization of the electromagnet 91 to move away from the back stop 93 and into engagement with the front stop 94.

45 One terminal of the battery 95 is connected to the armature 92, and the alarm bells 96, 96, are serially connected between the other terminal of said battery 95 and the relay front stop 94. It is thus evident that, whenever the armature 92 moves to its attracted position, a current path from the 50 battery 95 will be established through the bells 96, 96, thus causing these bells to sound in response to each energization of the magnet 91. In order to clearly manifest the code signals of the initiating stations N and N', in the system illustrated, it is desirable that

the bells 96, 96 should be of the single stroke type.

A well-known form of reduced-current constant-test equipment is connected to the front and back contacts 94 and 93, and comprises the high resistance relay magnet 101, which may be supplemented, if desired, by the resistor 102. The relay armature 103 is responsive to the magnet 101 and controls a current path including the battery 105 and the bell 106, so that upon the de-energization of said magnet 101, said bell will be caused to sound; so that, in the event of any interruption of the current path including the bells 96, 96, or any impairment 75 of the electromotive force of the current source 95 such as would decrease the current flow through the magnet 101 below a predetermined value, the armature 103 will act to close the circuit through the bell 106 80 and thereby give warning of such defective circuit conditions.

The parallel signal circuit loops, hereinbefore referred to, comprise current paths as follows:—one of said paths extends 90 through conductor 110 from one terminal of source B to terminal 34 of station N, thence through conductors 58 and 60, contacts 47, 45 and 46, and conductor 61 to terminal 35 of said station: thence through conductor 111 (including one winding of auxiliary responsive device Z, which will be hereinafter more fully referred to) to terminal 34 of initiating station N'; thence correspondingly through conductors and contacts of said station to terminal 35 thereof; thence through conductor 112 (including resistor R) to one end of the winding of the electromagnet 81 of the primary responsive device P; the other of said parallel loops extends from the other terminal of said magnet 81 through conductor 120 to terminal 33 of initiating station N, thence through conductor 57, contacts 44 and 43, conductor 68, contacts 53 and 52, and conductors 64 and 62 to terminal 36 of said station; thence through conductor 121 (serially including one terminal of each of the circuit closers C, C, C and the other winding of auxiliary responsive device Z) to the terminal 33 of the initiating station N'; thence correspondingly through the conductors and contacts of said station to terminal 36 thereof; thence through conductor 122 (serially including one terminal of the circuit closers C', C', C') to one end of the winding of electromagnet 91, through said winding, and conductor 123 to the other terminal of source B.

105 From the foregoing it will be seen that the primary device P and the resistor R are connected between one end of one of said loops and the opposite end of the other of said loops, and that the secondary responsive device S and the current source B are con- 110
115
120
125
130

nected between the remaining ends of said loops; thus providing one current path from one terminal of said source B, through the initiating stations N and N' in desired sequence, to one terminal of the primary responsive device P, and a second current path from the other terminal of said source B, through said stations N' and N in reverse sequence, to the other terminal of said primary device; the secondary responsive device S being included in one of said paths between the source B and said stations.

It will further be seen that the auxiliary responsive device Z is included in both of the current paths between stations N and N', and may therefore respond to current flow in either of said paths. The auxiliary responsive device Z may be employed in lieu of or in addition to either the primary responsive device P or the secondary responsive device S; although, for reasons which will be hereinafter more fully pointed out, an auxiliary responsive device included in the current paths in the manner indicated for the responsive device Z, should preferably be arranged for operation as a secondary device.

Inasmuch as the electromagnets of primary responsive devices should be effectively energized by the normal current flow through the comparatively high resistance connection between the conductors 112 and 120, it is evident that substantially higher resistance windings will be required for such magnets than would be needed to render them responsive to secondary signal closures, such as should cause the energization of magnet 91; for this reason, if windings of primary responsive devices are connected between initiating stations in the manner indicated for the device Z, the resistance of the current path for secondary signal closures will be substantially increased, and thus require the use of a current source B of greater electromotive force than would otherwise be necessary. On the other hand, if it is desired that any primary device should manifest both primary and secondary code signals, such device should be connected in the circuit in the manner shown for the device Z, so that one winding or the other of said device will form part of the current path of all secondary signal closures.

When an auxiliary device, such as the device Z, is employed for the manifestation of secondary code signals only, it is desirable that the independent electromagnet windings thereof should be differentially connected in the respective circuit loops so as to decrease the effectiveness of the energization thereof in response to primary signal closures.

It should be noted that although the local responsive devices L and L' and the auxiliary responsive device Z are represented as

main line bells and the general responsive devices P and S are represented as comprising local circuit or relay controlled bells,—such representations are employed simply for convenience in illustration, and form no part of this invention, as either main line or local relay circuit responsive devices may be employed, such devices may be of the so called "direct-acting" or the so called "electro-mechanical" type either "single stroke" or "continuous-ringing", and arranged to provide any desired form of either visible or audible signal manifestations, without departing from the spirit of this invention. In view of the functioning of the bells 86 and 106 as so called "trouble-bells" it will probably be ordinarily preferable that same should be of the "continuous-ringing" type and, for convenience, supplied by local batteries or current sources independent of the sources B and 95. Suitable single stroke primary and secondary responsive devices, such as bells or other responsive devices employed in place thereof, may be of the direct-acting type and directly included in the signal circuit loops. If duplication of primary or secondary responsive devices is required, same can be supplied either by extending local circuits such as those of relays 81 and 91, as suggested by the extension circuit provided for the alarm bells 96, 96; although additional primary responsive devices may be connected either in extensions of conductors 112 or 120, and additional secondary responsive devices may be connected in extensions of either conductors 110, 122 or 123; or such additional responsive devices may be connected in conductors extending from one initiating station to another (such as the conductors 111 and 121) in the manner in which the connections for auxiliary responsive device Z are shown.

If it is desired to associate a plurality of local responsive devices with any one station, such devices may be serially connected in conductor 69 or 70. If one or more initiating stations have no local responsive devices associated therewith, the terminals 31 and 32 of such stations should be connected by a suitable conductor. If there are not a like number of local responsive devices associated with each of the initiating stations included in any one signal circuit, it will, under some circumstances, be found to be desirable to include suitable resistance in the current path between the terminals 31 and 32 of stations with which a lesser number of responsive devices are associated, in order to prevent excessive current flow during secondary signal closures, such as will be hereinafter more fully described.

The current source B provides an electromotive force sufficient to cause effective en-

ergization of the electromagnet 91 through a current path including the winding of said magnet, one of the local responsive devices L, L' (or a larger number of such responsive devices if operating conditions provide for the concurrent inclusion of a plurality of such devices in any secondary signal current path) and one of the windings of each auxiliary responsive device Z 10 (if any of such devices are employed).

The connection between conductors 112 and 120 should be of such resistance that the current flow from the source B there-through will be insufficient to cause effective energization of the electromagnet 91; said connection will therefore be hereinafter termed, for want of a better designation, "a connection of comparatively high resistance." Such resistance may be provided 15 by the winding of the electromagnet 81, by the resistor R or jointly by said winding and said resistor. The resistance of one or the other of the windings of any auxiliary responsive device included in the signal circuit (such as the device Z) will take the place of a corresponding resistance in the winding of the magnet 81 or in the resistor R, as both of the windings of such auxiliary devices are included in the current path 20 through the magnet 81 and the resistor R, while one or the other of such auxiliary device windings is excluded from the secondary signal impulse current paths, as will be hereinafter more fully explained.

30 In order to minimize the normal discharge from the source B, the resistance of the current path between the ends of conductors 112 and 120 may be substantially greater than that merely sufficient to prevent current flow through said path of such intensity as to cause effective energization of the electromagnet 91; but the resistance of said path should not be so great as to require an unduly sensitive adjustment of primary 35 responsive devices.

The responsive device P should be so adjusted as to give the intended warning (as by the ringing of the bell 86) whenever the normal current flow through the signal circuit is interrupted, or is decreased below a predetermined strength; to the end that warning will be given whenever the normal signal circuit current path is interrupted, either incident to the transmission of a signal or because of an accidental rupture of some conductor; and to the further end that suitable warning will be given in the event that the electromotive force of the source B falls to a value deemed insufficient to adequately assure the intended operation of the 40 signaling system.

Referring now more particularly to Fig. 2—the armature 131 is mounted in responsive relation to the poles of the electromagnet 38, said armature being secured to the

detent lever 132, which lever is pivoted at 133 and carries the detent lug 134 which is normally disposed in the path of the detent arm 135, which arm is moved by some part of the signaling train (as, for example, the escapement pallet). Said armature, detent lever, lug and arm therefore constitute magnet-operated releasing means, for the signaling train which will be hereinafter more fully described.

75 Almost any well-known normally wound type of clockwork suitable for use in signal transmitting trains could be employed for operating the code wheel 54, the detent arm 135 and the notched disc 136, which will be 80 hereinafter referred to in greater detail. The winding shaft of such a train is indicated at 137, suitable gearing (not shown) acting through the intermediate shaft 138 to drive the code wheel shaft 139, the escapement wheel shaft 140, and the pallet shaft 141. As the details of such clockwork form no part of this invention, other details thereof are, in the interests of brevity and clearness, omitted from the drawings and from 90 this specification.

95 The disc 136 is secured to the shaft 139, and said disc has a notch 142 formed therein in position to receive the foot 143 of the detent lever 132 when the code wheel 54 and arm 42 are in their respective normal positions, as indicated by Fig. 1. Said notch is of such width as to prevent the entrance of the foot 143 therein other than while the arm 42 is positioned to lift the contact 39 100 into engagement with the contact 40 and away from the contact 41 and while the first tooth of the code wheel 54 is holding the contact 52 in engagement with the contact 53. It will thus be seen that the disc 136 105 with its notch 142, and the foot 143 constitute mechanical holding means so moved by the running of the train shaft 139 as to hold the detent lug 134 in operated position 110 (out of the path of the detent arm 135) whenever the magnet connection is rendered 115 ineffective by the periodically operated circuit controlling means contacts 39 and 40 or incident to the actuation of the formulating means contacts 52 and 53; and it will further be noted that said holding means assures a recurrent cycle of the action of said train in that, when the detent lug 134 is withdrawn from the path of the detent arm 135, the resultant rotation of the shaft 139 will carry 120 said notch out of the path of the foot 143, and will thus prevent the lug 134 being again carried into the path of the arm 135 until the shaft 139 has turned far enough to again bring the notch 142 into the path 125 of the foot 143, thus having completed substantially one revolution of the disc 136, arm 42, code wheel 54 and parts rotating therewith. Inasmuch as the notch 142 is 130 presented to the foot 143 at the conclusion

135

of each rotation of the code wheel 54, it is evident that such code wheel will act to formulate a greater or less number of the cycles or rounds of its signal, as determined by the effectiveness of the magnet 38 after each of such cycles; and that the magnet-operated releasing means will cause the train to operate the periodically actuated circuit controlling means a greater or less number 10 of times as determined by the effectiveness of said magnet 38 during the part of each cycle of said circuit controlling means during which the arm 42 of said means holds the contact 39 in engagement with the contact 40.

The electromagnet 38 is provided for operating the detent lever 132 so as to suitably trip and control the train. The winding of said magnet is connected in a branch current path, one end of which is connected through the conductor 66, contacts 40 and 39, and the conductors 59 and 58 to the terminal 34 of one of the circuit loops, and the other end of said branch path extends 25 through the conductor 67, to the contact 50 of the progressively operated circuit controlling means, from which said branch path may be completed through contact 49, conductor 65, terminal 37, conductor 71, and 30 any one of the circuit adjusters, C, C, C, to the conductor 121 of the other circuit loop. When the contact 48 is held in engagement with the contact 49, said branch magnet path is connected from the contact 35 49 to said other loop conductor 121 through said contact 48, conductors 63 and 62 and terminal 36; thus shunting the circuit adjusters C, C, C.

From the foregoing, it is apparent that 40 the arm 42 and the cooperating contacts 39 and 40 provide means for rendering the magnet connection ineffective, by the interruption thereof, during formulating breaks.

The latch arm 144 is mounted upon the 45 shaft 145 and turns freely thereon, said arm being provided with a face 146 adapted to cooperate with the projection 147 carried by the detent lever 132 so that when said projection occupies the position (as shown) 50 which it assumes when the armature 131 is in retracted position, said arm 144 will be permitted to move in the direction of said projection a greater distance than when said projection is in the position which it 55 occupies when said armature is in its attracted position.

Although the diameter of the disc 136 is such as to hold the foot 143 high enough (except when the notch 142 is presented to 60 said foot) to prevent the lug 134 from being brought into the path of the arm 135; the diameter of said disc is insufficient to raise said foot high enough to bring the projection 147 into the path of the face 146. Hence 65 said projection will be held in the path of

said face only during the energization of the magnet 38.

The cam 51 is fixed upon the shaft 145, and is of insulating material. The toothed sector 148 is also fixed upon the shaft 145, 70 and is mounted in suitable relation to the cam 51 so that said cam will be caused to operate the contacts 43, 48 and 50 in a suitable manner.

A suitable spring or gravity operated 75 means (not shown) is provided for constantly applying a tendency to the shaft 145 for clockwise rotation, and a stud 149 is carried by the sector 148; said stud being disposed in the path of the arm 144 and in such relation thereto as to engage said arm for the purpose of arresting the clockwise rotation of said sector. The actuating pin 150 is carried by the disc 136, and said pin is so positioned with relation to the sector 148 that, when said disc is in the position which presents the notch 142 to the foot 143, said pin 150 will be out of the path of the teeth of said sector 148; and so that, during the rotation of said disc 136, said pin will move 80 through the path of the teeth of said sector, to the end that said pin may engage some one of said teeth and move said sector in counter-clockwise direction an angular distance somewhat in excess of that between 85 adjacent tooth faces. Said pin 150 is further so positioned with relation to the arm 42 that the final part of the actuation of the sector 148 by said pin 150 will occur during 90 the portion of the rotation of said arm 42 in which said arm holds the contact 39 in engagement with the contact 40.

A holding pawl 151 is mounted on the shaft 152 and is arranged to engage the teeth of the sector 148, so that it may retain movement imparted to said sector 148 by the pin 150, against the tendency to clockwise movement constantly imparted thereto. An ear 153, carried by the pawl 151, cooperates with the ledge 154 which is formed on the side of the arm 144 so that when said pawl is in holding relation with any tooth of the sector 148 said ear will prevent movement of the arm 144 to such position as would bring the face 146 into the path of the projection 147, and so that, when the under side of said pawl is raised by engagement of any tooth of the sector 148 therewith, said ear 153 will be raised high enough to permit the ledge 154 to pass thereunder.

A suitable tendency is constantly imparted to move the arm 144 in the direction of the projection 147, so that when the sector 148 is moved counter-clockwise by the pin 150, if the projection 147 is not in its elevated position at the time when the pawl 151 is raised by the point of a tooth of the sector 148, the ledge 154 will pass under the ear 153 and thus support the pawl 151 in such elevated position; thereby permitting the sector 148 120

to swing in clockwise direction to its normal position as soon as the pin 150 moves out of the path of the teeth of said sector. When the sector 148 swings clockwise while the pawl 151 is supported by the engagement of the ledge 154 with the ear 153, the stud 149 will be brought against the side of the arm 144 and will swing said arm so as to withdraw the ledge 154 from the path of the ear 153, before said arm strikes against the side of the shaft 152 and thereby stops the clockwise movement of said arm and of the sector 148.

If the projection 147 is in its elevated position while the point of any one of the teeth of the sector 148 is passing under the end of the pawl 151, the engagement of the face 146 with said projection 147 will prevent the arm 144 from swinging to a position which would carry the ledge 154 into the path of the ear 153, and said pawl will therefore be permitted to move into holding relation with such tooth after the point thereof has moved to the left of the end of said pawl.

From the foregoing it will be apparent that if the magnet 38 is de-energized while the point of a tooth of the sector 148 is passing under the end of the pawl 151 just before the conclusion of any cycle of the transmitting mechanism, the sector 148 will be restored to its normal position, at the conclusion of such cycle; and that if such magnet is energized throughout each occasion when the ear 153 is lifted high enough to permit the ledge 154 to pass thereunder at the conclusion of each of a plurality of the cycles of the running of said transmitter, the movement of the sector 148 will be cumulatively progressive.

If the movement imparted to the sector 148 is progressively continued until the tooth 155 rests against the end of the pawl 151, it is evident that the actuation next thereafter imparted to said sector by the pin 150 will not elevate the pawl 151, as the periphery of said sector between the holding face of the tooth 155 and the end 156 of said sector is substantially equidistant from the shaft 145, and said pawl will therefore be permitted to drop into the path of said end 156 at the conclusion of the last step of the actuation of said sector by the pin 150, regardless of the action of the magnet 38 subsequent to the passage of the tooth 155 to the left of the end of the pawl 151.

The pawl 151 is provided with a handle 157 which facilitates the manual disengagement of said pawl from the sector 148 when said sector has been moved to its extreme left-hand position; said parts therefore provide manually operable means for restoring the progressively actuated circuit controlling means to normal condition after said controlling means has been uninterruptedly operated by the train throughout the maxi-

num number of cycles for which the train is intended to act without manual restoration.

The rise 158 of the cam 51 is so positioned with relation to the contact 50 that said rise will pass under the end thereof without moving said contact away from the contact 49; said rise is also arranged with relation to the contact 48 so that, when brought into engagement therewith, said contact will be moved into engagement with the contact 49.

The rise 159 of the cam 51 is arranged to engage the contact 43 to move said contact away from the contact 44 and into engagement with the contact 45, and so as to thereby move said contact 45 away from the contacts 46 and 47; and said rise 159 is further arranged so that when brought into engagement with the contact 50, said rise will move the contact 50 away from the contact 49.

The cam 51 is so set with relation to the sector 148 that, when said sector is in its extreme right-hand or fully restored position, neither of said rises will engage the contacts which cooperate therewith; and so that, when said sector is moved to the left an angular distance corresponding to that occupied by three of the teeth thereof, the rise 158 will move the contact 48 into engagement with the contact 49 and the rise 159 will move the contact 43 away from the contact 44 and into engagement with the contact 45, thereby moving said contact 45 away from the contacts 46 and 47. Although the rise 158 is shown as being so positioned with relation to the free end of the contact 48 as to move said contact into engagement with the contact 49 when the sector 148 is moved to the left a distance corresponding to that occupied by three of the teeth thereof; it is evident that, by altering the relationship of said rise and said contact, the progressively operated controlling means may be arranged so as to move the contact 48 into engagement with the contact 49 after any desired one or more cycles of the running of the train. The engagement of the contact 43 by the rise 159, incident to the step of the progressive actuation of the sector 148 which causes the rise 158 to actuate the contact 48, assures that the circuit adjusters 'C, 'C, 'C will be shunted when the signal train has uninterruptedly acted to and after the completion of three of the formulating cycles of the code wheel 54. Such assurance arises from the fact that the insulating cam 51 of the circuit controlling means is actuated by the cooperation of the pin 150 with the sector 148, and such actuation is rendered accumulatively progressive when the arm 144 permits the holding pawl 151 to effectively engage said sector, so that the contact 48 is moved into engagement with the contact 49 and thereby establishes a connection, be-

105
110
115
120
125

130

tween the branch magnet path and the conductor 62, which connection shunts the circuit adjusters C, C, C. The maintenance of such shunt will result in the energization 5 of electromagnet 38 during the test periods which occur near the end of each succeeding formulating cycle; to the end that, after the train has uninterruptedly acted to accomplish the formulating cycle a predetermined 10 one or more times, the timely energization of the electromagnet will not be dependent upon the continuity of the closure of the normally open contacts of any of the circuit adjusters C, C, C.

15 The angular movement of the rise 159, from the normal position thereof to such position as to enable said rise to move the contact 50 away from the contact 49, is substantially the same as the angular movement 20 of the sector 148 from the normal position thereof to such position as will permit the end of the pawl 151 to engage with the end 156 of said sector.

The shoulder 160 of the cam 51 is so 25 positioned with relation to the contact 43 and the sector 148 that, when said sector is swung to the left far enough to permit the end of the pawl 151 to engage the end 156 of said sector, said shoulder will be 30 withdrawn from the path of the contact 43, thereby permitting said contact to return to its normal position.

When the contact 43 has been moved by 35 the cam 51 so as to engage the contact 45, and the contact 39 rests upon the contact 41, an interconnection is provided between conductor 58 of one of the independent transmitter current paths and conductor 62 of the other of said paths. The interconnection 40 thus established is so situated, with relation to the code signal formulating contacts 52 and 53, that said contacts will be included in the portion of one loop extending from the interconnection to the current 45 source B, and said interconnection comprises the following current path,—from the conductor 62, through contacts 52 and 53, through conductor 68, through contacts 43 and 45, through conductor 56, terminal 32 50 and conductor 70 to and through local responsive device L thence through conductor 69, terminal 31, conductor 55, contacts 41 and 39, and conductor 59, to conductor 58.

It is evident that such interconnection is 55 normally ineffective, and will be rendered effective only after a predetermined cycle of the operation of the signal transmitting train, which cycle comprises, in the arrangement shown, two complete revolutions of 60 the code wheel 54; and that said interconnection will then be rendered effective only after such cycle has been uninterruptedly accomplished. It is also evident that the interconnection is rendered effective only by 65 the joint action of the periodically operated

circuit controlling means, comprising the arm 42 and the contacts 39 and 41, and the progressively operated circuit controlling means, comprising the insulating cam 51 and the contacts 43 and 45; which therefore 70 jointly constitute means operable by the signal train in running to interconnect the independent transmitter current paths, which form parts of respective loops of the signal circuit, throughout certain of the cycles of 75 the running of said train.

Although the progressively actuated mechanism shown is arranged so that the cam 51 is so controlled by the running of the train as to render said interconnection effective 80 immediately following the conclusion of two revolutions of the code wheel shaft 139, it is evident that the free end of the contact 43 could readily be so positioned with relation to the rise 159 that said interconnection would be rendered effective by and during the running of the train uninterruptedly continued to and after any desired number of formulating cycles of the code wheel 54; it is also evident that the effectiveness of 85 said interconnection could be controlled by means operable independently of said train; and the feature of this invention, whereby code signal mechanism is operable either with or without an interconnection in a circuit such as shown, is not limited to the control of such interconnection by the running 90 of the train.

The contacts 52 and 53 are effective for 95 the control of the current flow from the source B regardless of the effectiveness of the interconnection; hence each signal initiating station comprises the code signal mechanism including said contacts, which contacts are operable for the formulation of 100 code signals in the signal circuit either with or without an interconnection, as determined by the position of the cam 51 during respective formulating cycles. Although the code signal formulating contacts 52 and 53 are 105 shown as being connected in a particular one of the signal circuit loops, it is evident that, for the present purposes, these contacts may be serially included in either of the loops but that said contacts should, in any event, 110 be so connected as to be included in the portion of a loop which is situated between the current source and the interconnection of the station of which such contacts form part.

While the interconnection of any initiating station is effective, it provides a current path from the source B, including the code contacts 52 and 53 of such station, which path shunts the high resistance connection between conductors 112 and 120. It is likewise evident that when the train acts uninterruptedly to and after the completion of such number of formulations of the code signal as to cause said interconnection to be established, both of the normally closed in- 115 120 125 130

dependent current paths of such initiating station will be broken; one of said paths being broken when the contact 43 moves away from the contact 44, and the other of 5 said paths being broken when the contact 45 moves away from the contacts 46 and 47. The breaking of the independent current paths, as just described, will serve to break both loops of the signal circuit in the portions thereof which extend from said interconnection to the high resistance connection provided between the conductors 112 and 120.

As hereinbefore more specifically pointed out, the various stages of relation between 15 the contacts controlled by the cam 51, are only brought about when the operation of the train is uninterruptedly continued to and after a predetermined number of the cycles thereof. For certain classes of service, it 20 is unnecessary that such train operation should be uninterruptedly accomplished, prior to intended circuit adjustments.

When uninterrupted running of the train is not a necessary or desirable antecedent 25 to any of the contact actuations for which the cam 51 is intended, the arm 144 is omitted, thereby rendering the actuation of the sector 148 by the pin 150 cumulative and progressive regardless of the continuity of 30 the running of the train.

In the schematic diagram of Fig. 3, the initiating station terminals 31 to 37 inclusive are omitted, and, in the interests of convenience and clearness of diagrammatic representation, the cam 51 and the contact 43 are repeatedly indicated, thereby enabling the contacts cooperating therewith to be placed in the order of their sequence in the circuit. For like reasons: the primary responsive device P is represented as a single-stroke bell, the magnet of which is connected between the conductors 112 and 120 and the hammer of which is arranged to sound the bell in response to circuit breaks; and the secondary responsive device S is similarly shown, its hammer being arranged to sound its bell in response to circuit closures.

Operation.

The operation of the embodiment of this invention which is shown in Figs. 1 and 3 is as follows:

Under normal conditions the parts are in 55 the positions shown by said Figs. 1 and 3, all parts are at rest, the magnets 81 and 101 being effectively energized, and the current paths through the bells 86 and 106 being open. The magnet 91 is not effectively energized, and the current flow through the bells 96, 96 is insufficient to cause actuation thereof, because the resistor 102 and the magnet 101 are connected in the current path therewith. The current paths through 60 the local responsive devices L and L' are

broken between the contacts 39 and 41 of the initiating stations associated therewith; and the current paths through the electromagnets 38, 38 of such stations are broken between the contacts of the circuit adjusters 70 C, C, C and C', C', C' associated therewith, respectively.

If now the contacts of one of the circuit adjusters C, C, C are closed, a current path will be established through the electromagnet 38 in station N as follows: from one terminal of battery B, through conductor 110, terminal 34 of station N, conductors 58 and 59, contacts 39 and 40, conductor 66, the winding of said electromagnet, conductor 67, contacts 50 and 49, and conductor 65 to terminal 37 of said station; thence through conductor 71 and the closed contacts of such circuit adjuster C, to conductor 121; thence through said conductor and 75 through one winding of responsive device Z to terminal 33 of station N', thence through conductor 57, contacts 44 and 43, conductor 68, contacts 53 and 52, and through conductors 64 and 62 to terminal 90 36 of said station; thence through conductor 122 and the winding of magnet 91, and through conductor 123 to the other terminal of said source B. Inasmuch as the current path just described provides a shunt around 95 the high resistance connection between conductors 112 and 120, the current flow through said magnet 38 will be sufficient to cause effective energization thereof, but when so connected in parallel with the resistor R and magnet 81, the current flow through said paths will be insufficient to cause effective energization of the electromagnet 91.

When the electromagnet 38 is effectively energized, as just described, the armature 131 (see Fig. 2) will be moved into engagement with the poles of said magnet, thereby so swinging the lever 132 as to carry the lug 134 out of the path of the arm 135 and, incidentally, so as to carry the projection 147 into the path of the face 146; whereupon the signal train will rotate the disc 136 so as to withdraw the notch 142 from 105 the path of the foot 143.

Shortly after the notch 142 is thus withdrawn from the path of the foot 143, the continued rotation of the shaft 139 will swing the arm 42 out of the path of the contact 39, and said contact will thereupon move away from the contact 40 and thus break the current path through the magnet 38. Upon the interruption of the current flow through the magnet 38, the armature 131 will move away from said magnet until the foot 143 rests upon the disc 136. Said disc will then prevent such further movement of the armature 131 as would bring the lug 134 into the path of the arm 135. Fur- 110 120 125 130

ther rotation of the shaft 139 will then withdraw the first tooth of the code wheel 54 from the path of the contact 52, and said contact will thereupon move away from the 5 contact 53, thus interrupting the current flow in the signal circuit from the source B. Such interruption of the current flow from the source B will cause de-energization of the electromagnet 81, whereupon the armature 82 will move into engagement with the back stop 84, and thereby close the circuit from battery 85 through bell 86, thus causing said bell to sound. During continued movement of the code wheel 54, the signal 10 circuit will be alternately closed and broken between the contacts 52 and 53 of initiating station N, in conformity with the teeth provided upon said wheel; thereby causing the bell 86 to sound in a manner such as will 15 disclose the code signal of said station.

After the conclusion of one cycle of such code signal, the pin 150 will engage a tooth of the sector 148 and swing said sector to the left to the position shown in Fig. 2; and, 20 during such movement of said sector, the arm 42 will move the contact 39 into engagement with the contact 40, so that the branch current path through the electromagnet 38 may be rendered effective by any 25 one of the adjusters C, C, C before and throughout such movement of the sector 148 as will raise the end of the pawl 151 high enough to permit the ledge 154 of the arm 144 to pass under the ear 153 carried by 30 said pawl.

If, when the contact 39 is brought into engagement with the contact 40, as just described, the contacts of any of the circuit adjusters C, C, C are closed, the magnet 38 will be energized, thereby causing the armature 131 to swing the lever 132 so as to bring the projection 147 into the path of the face 146. As a result of such energization of the electromagnet 38, the arm 144 will be prevented from so swinging as to bring the ledge 154 into the path of the ear 153 when the engaging tooth of the sector passes under the end of the pawl 151, so that the pawl 151 will be permitted 45 to drop to the right of said tooth and prevent the restoration of the sector. Such energization of the electromagnet 38 will also prevent the foot 143 from dropping into the notch 142, and will therefore assure continued operation of the signaling 50 train for a second formulating cycle.

Had not the contacts of one or more of the circuit adjusters C, C, C been closed throughout the period while the engaging 60 tooth of the sector 148 supported the pawl 151 in a position which would permit the ledge 154 to pass under the ear 153, the resultant de-energization of the magnet 38 would have permitted the projection 147 to 65 remain below the path of the face 146, and

the arm 144 would have moved to the left and the ledge 154 would have passed under the ear 153, and would have thereby supported the pawl 151 when the pin 150 moved out of the path of the teeth of the 70 sector 148. Said sector would have thereupon returned to its normal position, carrying the pin 149 into engagement with the arm 144 and swinging said arm against the shaft 152. The various parts of the 75 progressively operated circuit controlling mechanism would have thus been restored to their respective normal positions. Had the magnet 38 become de-energized, as just described, the foot 143 would have dropped 80 into the notch 142, when said notch was presented thereto, and the lug 134 would therefore have moved into the path of the arm 135 and brought the train to rest.

At the conclusion of succeeding formulating cycles, like determinations will be made as to retention of the accumulating steps of the sector 148 and as to the continued running of the train. Such formulating cycles may thereafter be repeated 90 and such accumulating action of the sector may be continued until the end 156 passes to the left of the pawl 151.

Upon the actuation of sector 148 for the second step thereof from the position shown in Fig. 2, the cam 51 will move the contact 48 into engagement with the contact 49 and thereby cause a shunt to be established through conductors 121, 62 and 63 around the previously effective current path through the contacts of the circuit adjusters C, C, C so as to assure the continued running of the train regardless of any subsequent opening of the contacts of 100 said circuit adjusters. When the end 156 passes to the left of the end of the pawl 151, said cam will move the contact 50 away from the contact 49, and thus prevent further energization of the magnet 38. The train will therefore come to rest when the notch 142 is presented to the foot 143. After the train has been so brought to rest, the sector 148 will remain in fully accumulated position, and the train will be 105 unresponsive to closures of the circuit adjusters C, C, C until the pawl 151 has been manually moved out of the path of the teeth of the sector 148 (as by the handle 157), and said sector has thus been permitted to return to its normal position.

Whenever during the running of the train, as just described, the sector has been moved two accumulating steps thereof (i. e., one step to the left of the position shown in Fig. 2), the cam 51 will move the contact 43 into engagement with the contact 45, and will thus establish a current path such as will cause the local device L and the secondary device S to act 125 in response to each closure of the formulat- 130

ing contacts 52 and 53. The current path established during code signaling closures formulated under the conditions just described is as follows: From one terminal of source B, through conductor 110, to terminal 34 of station N; thence through conductors 58 and 59, contacts 39 and 41, and conductor 55, to terminal 31 of said station; thence through conductor 69, local responsive device L, and conductor 70, to terminal 32 of said station; thence through conductor 56, contacts 45 and 43, conductor 68, contacts 53 and 52, and conductors 64 and 62, to terminal 36 of said station; thence through conductor 121 (including one winding of responsive device Z) to terminal 33 of station N'; thence through conductor 57, contacts 44 and 43, conductor 68, contacts 53 and 52, conductors 64 and 62 to terminal 36 of said station; thence through conductor 122, through windings of electromagnet 91 of responsive device S, and through conductor 123, to the other terminal of source B. Such movement of the contact 43 will carry same away from the contact 44, and will cause the contact 45 to move away from the contacts 46 and 47, thus breaking the portions of both loops which extend from the interconnection of the station N to the primary device P, for reasons which will be hereinafter more fully explained.

Should the contacts of any one or more of the circuit adjusters C', C', C' of the initiating station N' be closed, the various parts of the signal transmitting mechanism of said station will respond in a manner similar to that in which the corresponding parts of the station N respond to a closure of corresponding duration of the adjusters C, C, C, as just described.

Should the contacts of one or more of the circuit adjusters C, C, C and one or more of the adjusters C', C', C' close at or about the same time, the magnets 38 of the initiating stations N and N' will be concurrently energized, and the trains of said stations will run concurrently for a time. If the contacts of one or more of the circuit adjusters C', C', C' are closed when the contact 39 is moved into engagement with the contact 40 of station N' at the conclusion of the first formulating cycle of said station, the operation of said station will continue without interruption for a second cycle regardless of the fact that the formulating mechanism of station N is also operating; but corresponding continued closure of contacts of the circuit adjusters C, C, C will not similarly continue operation of the station N, as the energization of the magnet 38 of said station is dependent upon the continuity of a current path including the code contacts 52 and 53 of station N'; hence the running of the signal train of station N will

be interrupted after the first formulating cycle thereof, unless it so happens that the contacts 52 and 53 of station N' are closed by some tooth of the code wheel 54 thereat while the notch 142 of station N is presented to the foot 143 thereof. In any event, when the sector 148 of station N has been moved one accumulative step thereof during the latter part of the first formulating cycle of the transmitting mechanism of such station, under the circumstances just described, it is evident that the electromagnet 38 of said station will not remain energized throughout the period during which the pawl 151 is supported by a tooth of said sector in such elevated position as to permit the ledge 154 to pass under the ear 153, because said electromagnet will be energized only during closures of the formulating contacts 52 and 53 of station N', and none of such closures are co-extensive in duration with the aforesaid period. Hence the arm 144 will carry the ledge 154 to the left and into the path of the ear 153, thereby preventing the pawl 151 from effectively engaging the teeth of the sector 148 and permitting said sector to return to its normal position, immediately after the pin 150 has moved out of the path of said teeth.

Although, as already pointed out, the transmitting mechanism of the station N will probably come to rest at the conclusion of the first formulating cycle thereof, it is evident that if the contacts of any of the circuit adjusters C, C, C remain closed, the electromagnet 38 of station N will be again energized during any closure of the contacts 52 and 53 of station N' incident to the second formulating cycle of said station, which closure occurs next after the notch 142 is presented to the foot 143 of station N; and that the performance of the transmitting mechanism of said station N incident to the first formulating cycle thereof will thereupon be repeated.

After the second formulating cycle of the station N', the pin 150 will move the sector 148 thereat a second step, the retention of which step will be dependent upon the timely energization of the electromagnet 38 of said station, as already explained. Such second accumulative step of said sector 148 will cause the cam 51 of said station N' to move its contact 43 away from the contact 44 and into engagement with the contact 45 associated therewith, thereby moving said contact 45 out of engagement with its associated contacts 46 and 47. While such contacts of station N' are in such altered position, it is evident that the electromagnet 38 of station N will not be energized, even during closures of the code contacts 52 and 53 of station N', because the separation of the contacts 44 and 43 of station N' interrupts the current path through conductor

121 upon which the energization of the electromagnet 38 of station N is dependent. If, during and subsequent to the actuation of the sector 148 of station N', under 5 the conditions just referred to, the contacts of one or more of the circuit adjusters C', C', C' remain closed,—such accumulative step will be retained and the running of the transmitting mechanism of said station will 10 continue throughout the third formulating cycle thereof. The engagement of the contact 45 by the contact 43 of station N' will afford a current path including the local responsive device L' during each closure of 15 the formulating contacts 52 and 53 incident to such third formulating cycle of said station. The current path through the local responsive device L' provides an interconnection between the respective loops of the 20 signal circuit, as hereinafter described, the resistance of which interconnection is sufficiently low to assure the effective energization of the electromagnet 91. From the foregoing it will be apparent that both the 25 primary responsive device P and the local responsive device L will act to manifest the code signaling impulses which are formulated during the effectiveness of the interconnection at station N'. The current path 30 established during code signaling closures formulated under the conditions just described is as follows:—from one terminal of source B, through conductor 110, to terminal 34 of station N; thence through conductors 35 58 and 60, contacts 47, 45 and 46, and conductor 61, to terminal 35 of said station; thence through conductor 111 (including one winding of responsive device Z) to terminal 34 of station N'; thence through conductors 40 58 and 59, contacts 39 and 41, and conductor 55, to terminal 31 of said station; thence through conductor 69, local responsive device L', and conductor 70, to terminal 32 of said station; thence through conductor 56, 45 contacts 45 and 43, conductor 68, contacts 53 and 52, and conductors 64 and 62, to terminal 36 of said station; thence through conductor 122, through winding of electromagnet 91 of responsive device S, and 50 through conductor 123, to the other terminal of source B.

After the third formulating cycle of the station N', under the conditions just described, the sector 148 will be moved a third step by the engagement therewith of the pin 150. During such third step, the rise 158 of the cam 51 will move the contact 48 into engagement with the contact 49, thereby shunting the circuit adjusters C', C', C'; whereupon 55 the running of the signal train of said station will continue until such additional formulating cycles have been accomplished as will cause the sector 148 to be moved by the pin 150 to the position where the end 60 156 may be engaged by the pawl 151; where-

upon the rise 159 will move the contact 50 away from the contact 49, and the withdrawal of the shoulder 160 from the path of the contact 43 will permit said contact and the contact 45 to return to their respective 70 normal positions.

The separation of contact 50 from contact 49, as just described, will prevent further energization of the magnet 38 of station N', and the signaling train of such station will 75 therefore come to rest as soon as the notch 142 of the disc 136 therein is again presented to the foot 143 after such separation of said contacts.

The restoration of contacts 43 and 45 to 80 their respective normal positions, as just described, will prevent the re-establishment of the current path through the interconnection of the station N', thus preventing further actuation of the local device L', and 85 will re-establish the normal current paths of both loops of the signaling circuit.

If, upon the restoration of the contacts 43 and 45 of station N', as just described, the contacts of one or more of the circuit 90 adjusters C, C, C are closed, the magnet 38 of station N will be energized and said station will operate in the manner hereinbefore described, dependent upon the duration of such contact closure. As already pointed out, portions of both loops of the signal circuit are interrupted by the circuit controlling means throughout the effectiveness of the interconnection of any initiating station, such interruptions being positioned in the 100 portions of said loops extending from the interconnection toward the high resistance connection between said loops, as most clearly indicated by Fig. 3. It is evident that, while the contacts 43 and 44 of station 105 N' are thus interrupting the loop comprising the conductors 120, 121 and 122, the energization of the electromagnet 38 of initiating station N will be prevented; and that the same would be true as to any other 110 stations so connected in the signal circuit as to be dependent, for the energization of the electromagnets thereat, upon the portion of said loop which extends from said station N' toward the high resistance connection 115 comprising the device P and the resistor R, even should the contacts of one or more of the circuit adjusters associated therewith be closed; hence the signal transmitting trains of such stations will not start during the 120 effectiveness of the interconnection at station N', and, should the train of any such station be running at the time said interconnection becomes effective, such train will be brought to rest as soon as the notch 142 of the disc 136 of such station is presented to its co-acting foot 143, and the sector 148 of any such station will be restored to its 125 normal position. Running of the train of station N during the effectiveness of the in-

130

terconnection at station N' would not interfere with the correct manifestation by the secondary device S of the signal of said station N', because the circuit path then effective through the contacts 52 and 53 of said station N' does not rely for its continuity, under these circumstances, upon the corresponding contacts of station N; said current path being as follows: from one terminal of source B, through conductor 110, to terminal 34 of station N; thence through conductors 58 and 60, contacts 47, 45 and 46, and conductor 61, to terminal 35 of said station; thence through conductor 111 (including one winding of responsive device Z) to terminal 34 of station N'; thence through conductors 58 and 59, contacts 39 and 41, and conductor 55, to terminal 31 of said station; thence through conductor 69, local responsive device L', and conductor 70, to terminal 32 of said station; thence through conductor 56, contacts 45 and 43, conductor 68, contacts 53 and 52, and conductors 64 and 62, to terminal 36 of said station; thence through conductor 122, through winding of electromagnet 91 of responsive device S, and through conductor 123, to the other terminal of source B. It is likewise evident that, while the circuit loop comprising the conductors 110, 111, and 112, is interrupted by the movement of the contact 45 away from contacts 46 and 47 of said station N, the energization of the electromagnet 38 of station N' is similarly prevented; and the same would be true as to any other stations so connected in the signal circuit as to be dependent, for the energization of the electromagnets thereat, upon the portion of said loop which extends from said station N toward the high resistance connection comprising the device P and the resistor R.

Absolute non-interference is thus attained between the various initiating stations, as to the transmission of signals therefrom in response to which the secondary device S should act.

If certain or all of the circuit adjusters associated with initiating stations are so arranged that the contacts thereof may be so closed that they will not again open without manual readjustment, such, for example, as are shown in the patent to Cortland, et al., No. 887,898, dated December 4, 1906; it is evident that, if such adjusters associated with a plurality of such stations are concurrently so closed, the code signals of all of such stations will be manifested by the secondary device S, one after another, in an orderly sequence; the station connected nearest to the source B in the loop comprising the conductors 120, 121 and 122 being at all times afforded precedence over stations connected in said loop more distantly from said source.

When the transmitting mechanism of two

or more initiating stations are acting concurrently during the first or second formulating cycles thereof, it is evident that the response of the primary device P will be irregular, and not in accordance with the code signals of any one of such stations; such irregularity of response will afford a warning that a plurality of stations are acting concurrently. In such a case the code signals of one or more of such stations will be subsequently manifested by the secondary responsive device S.

If the auxiliary device Z is arranged for response to the normal current flow through the high resistance connection comprising the electromagnet 81 and the resistor R, such device will respond to all primary and secondary signals; otherwise said auxiliary device will respond only to secondary signals.

When the handle 157 is moved to withdraw the pawl 151 from the path of the teeth of the sector 148, after said sector has assumed its fully accumulated or extreme left-hand position, during the movement of said sector, incident to the restoration thereof to its normal position, the contact 50 will be permitted to move into engagement with the contact 49 before the contact 48 is permitted to move away from said contact 49, and the electromagnet 38 associated therewith will therefore be momentarily energized. If the force supplied for moving the sector 148 is sufficiently great, the duration of the energization of the electromagnet will not be great enough to start the train; but if the duration of such period is somewhat extended, the train will start and thereby cause the primary device P to manifest one cycle of the code signal of the station so restored; thereby giving those in charge of the system assurance that the sector of such station has been restored. In any event, the engagement of the shoulder 160 with the contact 43 will move said contact to interrupt both loops of the signal circuit, thereby momentarily de-energizing the electromagnet 81.

Should any accidental break develop in any loop of the signal circuit or should the electromotive force of the source B fall below a predetermined value, the armature 82 of the device P will move away from the magnet 81 and cause the bell 86 to sound in response to the battery 85, thus giving suitable warning of such derangement of the system.

Referring now to Fig. 4 it will be seen that the circuit arrangement therein represented corresponds with that represented by Figs. 1 and 3, except as to the connection of the primary responsive device P', the winding of the electromagnet 81' of which is serially connected in the current path of the conductor 110, thus rendering said device responsive to both primary and secondary code signals.

- The action of the device P' will therefore be similar, under like circumstances, to that already described in connection with device Z , when such device Z is adjusted for response to primary signals. Otherwise, the operation of a system arranged in accordance with Fig. 4 will correspond with the description hereinbefore given with relation to Figs. 1 and 3.
10. Fig. 5 illustrates the application of certain features of this invention to a system so arranged that the normal current flow in the signal circuit thereof will be as great as that incident to the formulation of any code signal. The electromagnet $38'$ being differentially wound and having both of the windings thereof included in the normal signal circuit current path. Upon the closure of the contacts of a circuit adjuster, such as the 15 circuit adjuster c of the station n , one winding of the electromagnet $38'$ of such station will be short-circuited, thus causing the effective energization of such magnet.
- The contact $48'$ of each of the stations is 20 operable by both the rise 158 and the rise 159 of the cam 51; the rise 158 serving to move said contact $48'$ into engagement with the contact $49'$, and thereby maintain the short circuit around one winding of the electromagnet $38'$ independently of the contacts 25 of the adjuster c . The additional movement imparted to contact $48'$ by the rise 159 moves the contacts $48'$ and $49'$ so as to bring said contact $49'$ into engagement with the contact $50'$, and to thereby short-circuit both 30 windings of the magnet $38'$ to prevent effective energization thereof.
- The contacts 40, 45, 46 and 47, of Figs. 1, 3 and 4, are omitted, thus rendering devices 35 1, 1' responsive to all signals formulated by the initiating stations associated therewith, and failing to provide for the interruption of the circuit loop comprising the conductors 110, 111 and 112 during the formulation of any code signal.
- The arm $42'$ resembles the arm 42 hereinbefore described in greater detail, but differs therefrom in that, as shown in Fig. 5, said arm $42'$ is so formed as to present a shorter 40 peripheral portion to the contact 39; and is so positioned with relation to said contact 39 as to hold same away from the contact 41 throughout the period when the notch 142 is 45 presented to the foot 143 (i. e., while the train is in the position which it occupies when at rest) and to permit said contact to engage during the running of the train immediately after the notch 142 is withdrawn from the path of the foot 143, and before 50 the first break between contacts 52 and 53 incident to rotation of the code wheel 54 associated therewith, so that said contacts 39 and 41 will be in engagement during part 55 of the closure preceding the first break and

throughout all succeeding closures incident 65 to the rotation of said code wheel.

The operation of a system arranged in accordance with Fig. 5 is as follows:

Under normal conditions the parts are at rest and the various contacts occupy the respective positions shown by the drawing, establishing a current path from one terminal of the source B , through conductor 110, and winding of electromagnet $81'$ of responsive device P' , through conductors 111 and 112 through contacts 44 and 43 of station n , through conductor 68, contacts 53 and 52, conductor 64, and differential windings of electromagnet $38'$ of said station, thence 70 through conductor 121 including one of the contacts of adjuster c , through contacts 44 and 43 of station n' , through conductor 68, through contacts 53 and 52, through conductor 64 and the differential windings of the electromagnet $38'$ of said station, thence 75 through conductor 122, and one contact of adjuster c' to the other terminal of source B .

The establishment of the current path just described will cause the effective energization of the electromagnet $81'$, and will therefore prevent signal manifesting action of the device P' ; such current flow will not, however, cause effective energization of the electromagnet $38'$ of the initiating stations, 80 since such current path effectively includes both of the windings of each of such magnets, and said windings are differentially connected in said current path.

In the event of the closure of the contacts 85 of adjuster c , while the circuit is in normal condition, as just described; one of the differential windings of the electromagnet $38'$ of station n will be short-circuited, and the current flow through the other winding of 90 said magnet will thereupon cause effective energization thereof.

Upon such energization of the electromagnet of said station, the signaling train thereat will act to move its arm $42'$ out of the path of the contact 39, and said contact will thereupon move into engagement with the contact 41; thus establishing an interconnection, including the responsive device l , 100 between the circuit loop comprising the conductors 110, 111 and 112 and the circuit loop comprising the conductors 121 and 122. Inasmuch, however, as the current path through the responsive device l will, under 105 the circumstances just described, be shunted by a current path comprising the conductor 68 and the contacts 43 and 44 of said station, and the conductors 112 and 111, the current flow through said device will be insufficient 110 to cause the actuation thereof.

During the running of the signaling train of station n , under the conditions just described, the device P' will act in response to

each circuit break caused by the separation of the contact 52 from the contact 53 of said station.

If the contacts of the adjuster *c* remain closed for but a comparatively brief period, the formulating train of station *n* will come to rest after one or more formulations of the code signal of said station such as that just described, dependent upon the duration of such period. Should the contacts of the adjuster *c* remain closed for an extended period, the consequent cumulative movement of the cam 51 will cause the rise 158 to move the contact 48' into engagement with the contact 49' and thus shunt the contacts of the adjuster *c*; and the rise 159 will move the contact 43 away from the contact 44 and thus interrupt the current path through the conductor 112 which had previously shunted the responsive device *l*. The engagement of the contact 48' with the contact 49' will thus assure the continued running of the train regardless of any subsequent opening of the contacts of the circuit adjuster *c*; and the movement of the contact 43 away from the contact 44 will cause the device *l* to respond to the subsequent actuation of the formulating contacts 52 and 53 of said station.

At the completion of a predetermined one or more formulating cycles, under the conditions just described, the rise 159 will move the contact 48' so as to carry the contact 49' into engagement with the contact 50', and thus prevent further energization of the magnet 38'. The train will therefore come to rest when the notch 142 is next presented to the foot 143.

Should the contacts of the adjusters *c* and *c'* close at or about the same time, the formulating mechanism of both stations would act concurrently for a time; during such concurrent action, all circuit breaks incident to the actuation of the formulating contacts 52 and 53 of station *n*' will cause response of the device *P*', and every closure of said contacts will cause energization of said magnet 81' of said device. The device *l*' would respond to all formulating closures, and the running of the train of station *n* would be interrupted during the separation of the contact 43 of station *n*' from the contact 44 thereof.

If the contacts of adjuster *c* remain closed after the shoulder 160 of station *n* has been withdrawn from the path of the contact 43 thereof, the transmitting mechanism of station *n* will act in response to the resultant effective energization of the magnet in the manner hereinbefore described.

From the foregoing it will be seen that the arrangement of Fig. 5 does not afford non-interference under all circumstances, but that, during the formulation of the code signal of any initiating station, the elec-

tromagnet of other stations will not be subject to energization in response to closure of the contacts of the adjusters thereat unless such other stations are connected in the portion of the loop comprising the conductors 121 and 122 extending from such operating station toward the source *B*.

The arrangement of Fig. 5 is therefore not suited to fulfill all of the requirements which would be successfully served by systems such as those indicated by Figs. 1, 3 and 4; but the arrangement of Fig. 5 may be employed when circumstances are such that it is deemed improbable that occasions for interference would develop other than in a predetermined sequence. For example, if the adjuster *c*' is arranged for response to temperature conditions in the lower part of a building, so that in the event of an excessive rise in temperature such adjuster will act to cause effective energization of the electromagnet 38' of station *n*', station *n* being similarly arranged with relation to the upper portion of the same building, it is apparent that should fire occur in the lower portion of the building, the action of the formulating mechanism of the station *n*' will proceed without interference, even though the heat rising from such fire should cause closure of the contacts of the adjuster *c* during the formulating action of the initiating station *n*'. On the other hand, it is quite evident that, under such conditions, it would be quite improbable that the heat from any fire which would serve to cause the contacts of adjuster *c* to close would travel downwardly to an extent which would cause the contacts of adjuster *c*' to close, prior to the conclusion of the formulating action of station *n* in response to such closure of the contacts of the adjuster *c* associated therewith.

Fig. 6 illustrates the application of certain features of this invention to a system having a primary responsive device *P* and a secondary responsive device *S* connected in a manner similar to that employed in the systems represented by Figs. 1 and 3, and having initiating stations comprising the code signal formulating contacts 52 and 53 and the interconnection establishing contacts 43 and 45 operable by cams 51 associated therewith.

Such initiating stations may be arranged to be set in motion by any desired manually or automatically operable means, but the starting thereof is not dependent upon current flow in the signal circuit.

It is evident that, during formulating actuation of initiating station *n*' of Fig. 6, the secondary responsive device *P* will act to manifest the code signal of said station while the contact 43 is not resting against the contact 45, and that while said contacts are in engagement, the device *S* will respond to

such formulating cycles regardless of any concurrent activity of the formulating mechanism of the station n shown by the figure.

From the foregoing, it will be observed 5 that a system such as that shown in Fig. 6 will afford non-interference functions between initiating stations dependent upon the sequence in which they are connected in the signal circuit, and similar to such functions 10 of this character as are provided by the system illustrated by Fig. 5; but that the actuation of such stations is independent of the responsiveness of the circuit thereto, so that the operation of the mechanism of station n would not be deferred during the formulating actuation of the station n' as would be the case in a system such as that shown in Fig. 5 under like circumstances.

On the other hand, a system such as that 20 shown by Fig. 6 provides facilities by which either primary or secondary signals may be transmitted from any initiating station, while a system such as that shown by Fig. 5 provides for but one class of such signals.

25 The structural features shown by Fig. 2, whereby movement of the sector 148 is only cumulatively progressive in response to uninterrupted running of the signaling train, does not form part of this invention, but 30 is more fully shown by and claimed in my co-pending application filed Dec. 7th, 1920, Serial No. 428,970; but I herein claim and desire to secure by Letters Patent of the United States of America:

35 1. In a signaling system: a current source; a resistor; signaling stations each comprising means for establishing two normally closed independent current paths therethrough, and signaling mechanism 40 comprising contacts so associated with said paths and with one another as to be operable to break one and to establish a connection between such one and the other of said paths; a signal circuit one side of which 45 extends from one terminal of said source to one terminal of said resistor and serially includes therebetween one of the current paths of each of said stations in desired sequence, and the other side of which extends 50 from the other terminal of said source to the remaining terminal of said resistor and serially includes therebetween the other of the current paths of each of said stations in reverse sequence; a primary device responsive to current flow in said signal circuit 55 during ineffectiveness of the interconnecting means of all signaling stations; and a secondary device responsive to current flow from said source only during effectiveness 60 of such interconnecting means.

2. In a signaling system: a current source; a resistor; signaling stations each having means for establishing two normally closed independent current paths there- 65 through, signaling mechanism comprising

contacts forming part of and operable to break and close one of said paths to formulate a desired code signal and means for establishing an interconnection between such paths; a signal circuit one side of which 70 extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence; a primary device responsive to current flow in said signal circuit during ineffectiveness of the interconnecting means of all signaling stations; and a secondary device responsive to current flow from said source only during 80 effectiveness of such interconnecting means.

3. In a signaling system: a current source; a resistor; signaling stations each having means for establishing two normally closed independent current paths therethrough, mechanism comprising contacts forming part of and operable to break and close one of said paths to formulate a desired code signal and means operable by and during action of said mechanism to establish an interconnection between such paths; a signal circuit one side of which extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence; a primary device responsive to current flow in said signal circuit during ineffectiveness of the interconnecting means of all signaling stations; and a secondary device responsive to current flow from said source only during effectiveness of such interconnecting means.

4. In a signaling system: a current source; a resistor; signaling stations each having means for establishing two normally closed independent current paths therethrough, mechanism comprising contacts forming part of and operable to break and close one of said paths to formulate a desired code signal a greater or less number of times, circuit controlling means operable by and during action of said mechanism to establish an interconnection between said paths, and means so governing such actuation of said circuit controlling means that said interconnection will be established only when actuation of said mechanism is uninterruptedly continued to and after the completion of a predetermined one or more for- 120

- a resistor; signaling stations each having means for establishing two normally closed independent current paths therethrough, mechanism comprising contacts forming 5 part of and operable to break and close one of said paths to formulate a desired code signal and circuit controlling means operable by and during action of said mechanism to establish an abnormal current path 10 comprising said contacts and parts of the two normally independent current paths and to break both of said normally independent current paths in parts thereof which are not included in such abnormal path; a signal 15 circuit one side of which extends from one terminal of said source to one terminal of said resistor and serially includes therebetween one of the current paths of each of said stations in desired sequence, and the 20 other side of which circuit extends from the other terminal of said source to the remaining terminal of said resistor and serially connects therebetween the other of the current paths of each of said stations in reverse 25 sequence, said signaling station current paths so connected in said circuit that the establishment of the described abnormal current path at any station will interconnect the portions of said signal circuit which most directly connect such station and said current 30 source; a primary device responsive to current flow in said signal circuit during ineffectiveness of the abnormal current paths of all signaling stations; and a secondary 35 device responsive to current flow from said source only during effectiveness of such an abnormal path.
9. In a signaling system: a current source; a resistor; local responsive devices; signaling stations each comprising means for interconnecting two normally independent current paths through an associated one of said local responsive devices; a signal circuit one side of which extends from one 40 terminal of said source to one terminal of said resistor and connects said stations in desired sequence therebetween, and the other side of which extends from the other terminal of said source to the remaining terminal of said resistor and serially connects therebetween the other of the current paths of each of said stations in reverse sequence; a primary device responsive to current flow in said signal circuit during ineffectiveness of the interconnecting means of all signaling stations; and a secondary device responsive to current flow from said source only during effectiveness of such interconnecting means.
10. In a signaling system: a current source; a resistor; local responsive devices; signaling stations each having mechanism comprising contacts operable to break and close one of two normally independent current paths to formulate a desired code signal 45 and means for establishing an interconnection between such paths, which interconnection includes an associated one of said local responsive devices; a signal circuit one side of which extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence; a primary device responsive to current flow in said signal circuit during ineffectiveness of the interconnecting means of all signaling stations; and a secondary device responsive to current flow from said source only during effectiveness of such interconnecting means.
11. In a signaling system: a current source; a resistor; local responsive devices; signaling stations each having mechanism comprising contacts operable to break and close one of two normally independent current paths to formulate a desired code signal and circuit controlling means operable by and during action of said mechanism to establish an interconnection between such paths, which interconnection includes an associated one of said local responsive devices; a signal circuit one side of which extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence; a primary device responsive to current flow in said signal circuit during ineffectiveness of the interconnecting means of all signaling stations; and a secondary device responsive to current flow from said source only during effectiveness of such interconnecting means.
12. In a signaling system: a current source; a resistor; signaling stations each having mechanism comprising contacts variably operable to break and close one of two normally independent current paths to formulate a desired code signal a greater or less number of times, circuit controlling means operable by and during action of said mechanism to establish an interconnection between said paths, and means so governing such actuation of said circuit controlling means that said interconnection will be established only when actuation of said mechanism is uninterrupted continued to and after the completion of a predetermined one or more formulations of said code signal; local responsive devices associated with respective signaling stations and included

in the interconnections thereat; a signal circuit one side of which extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence; a primary device responsive to current flow in said signal circuit during ineffectiveness of the interconnecting means of all signaling stations; and a secondary device responsive to current flow from said source only during effectiveness of such interconnecting means.

13. In a signaling system: a current source; a resistor; signaling stations each having mechanism comprising contacts operable to break and close one of two normally independent current paths to formulate a desired code signal and circuit controlling means operable by and during action of said mechanism to establish an interconnection between said paths; local responsive devices associated with respective signaling stations and included in the interconnections thereat; a signal circuit one side of which extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence, said signaling station current paths so connected in said circuit that the code signaling contacts of each station will be included in the portion of one of the current paths thereof which is situated between the interconnection of such station and said current source; a primary device responsive to current flow in said signal circuit during ineffectiveness of the interconnecting means of all signaling stations; and a secondary device responsive to current flow from said source only during effectiveness of such interconnecting means.

14. In a signaling system: a current source; a resistor; signaling stations each having mechanism comprising contacts operable to break and close one of two normally independent current paths to formulate a desired code signal and circuit controlling means operable by and during action of said mechanism to establish an abnormal current path comprising said contacts and parts of the two normally independent current paths and to break one of said normally independent current paths in

a part thereof which is not included in such abnormal path; local responsive devices associated with respective signaling stations and included in the abnormal current paths which may be established thereby; a signal circuit one side of which extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence, said signaling station current paths so connected in said circuit that the establishment of the described abnormal current path at any station will interconnect the portions of said signal circuit which most directly connect such station and said current source; a primary device responsive to current flow in said signal circuit during the ineffectiveness of the abnormal current paths of all signaling stations; and a secondary device responsive to current flow from said source only during effectiveness of such an abnormal path.

15. In a signaling system: a current source; a resistor; signaling stations each having mechanism comprising contacts operable to break and close one of two normally independent current paths to formulate a desired code signal, and circuit controlling means operable by and during action of said mechanism to establish an abnormal current path comprising said contacts and parts of the two normally independent current paths and to break the one of said normally independent current paths which is responsive to said code contacts in a part thereof which is not included in such abnormal path; local responsive devices associated with respective signaling stations and included in the abnormal current paths which may be established thereby; a signal circuit one side of which extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence, said signaling station current paths so connected in said circuit that the establishment of the described abnormal current path at any station will interconnect the portions of said signal circuit which most directly connect such station and said current source; a primary device responsive to current flow in said signal circuit during ineffectiveness of the abnormal current paths of all signaling stations; and a second-

ary device responsive to current flow from said source only during effectiveness of such an abnormal path.

16. In a signaling system: a current source; a resistor; signaling stations each having signaling mechanism comprising contacts operable to break and close one of two normally independent current paths to formulate a desired code signal, and circuit controlling means operable by and during action of said mechanism to establish an abnormal current path comprising said contacts and parts of the two normally independent current paths and to break both of said normally independent current paths in parts thereof which are not included in such abnormal path; local responsive devices associated with respective signaling stations and included in the abnormal current paths which may be established thereby; a signal circuit one side of which extends from one terminal of said source to one terminal of said resistor and serially includes therebetween one of the current paths of each of said stations in desired sequence, and the other side of which circuit extends from the other terminal of said source to the remaining terminal of said resistor and serially connects therebetween the other of the current paths of each of said stations in reverse sequence, said signaling station current paths so connected in said circuit that the establishment of the described abnormal current path at any station will interconnect the portions of said signal circuit which most directly connect such station and said current source; a primary device responsive to current flow in said signal circuit during ineffectiveness of the abnormal current paths of all signaling stations; and a secondary device responsive to current flow from said source only during effectiveness of such an abnormal path.

17. In a signaling system: a primary responsive device; a current source; a secondary responsive device; signaling stations; and a signal circuit comprising two parallel loops, said primary responsive device connected between one end of one of said loops and the opposite end of the other of said loops, said current source and said secondary responsive device connected between the remaining ends of said loops, and said signaling stations serially connected in both of said loops.

18. In a signaling system: a primary responsive device; a current source; a secondary responsive device; signaling stations each having means for establishing two normally closed independent current paths therethrough, code signaling mechanism comprising contacts forming part of and variably operable to break and close one of said paths either without or with an interconnection between such paths; and a sig-

nal circuit comprising two parallel loops, said primary responsive device connected between one end of one of said loops and the opposite end of the other of said loops, said current source and said secondary responsive device connected between the remaining ends of said loops, said signaling stations connected in both of said loops, and the two current paths of each station serially connected in respective ones of said loops.

19. In a signaling system: a primary responsive device; a current source; a secondary responsive device; signaling stations each having means for establishing two normally closed independent current paths therethrough, said means including code signaling mechanism comprising contacts variably operable to break and close one of such paths and means operable by and during the action of said mechanism to establish an interconnection between such paths; and a signal circuit comprising two parallel loops, said primary responsive device connected between one end of one of said loops and the opposite end of the other of said loops, said current source and said secondary responsive device connected between the remaining ends of said loops, said signaling stations connected in both of said loops, and the two current paths of each station serially connected in respective ones of said loops.

20. In a signaling system: a primary responsive device; a current source; a secondary responsive device; signaling stations each having means for establishing two normally closed independent current paths therethrough, said means including mechanism comprising contacts variably operable to break and close one of such paths to formulate a desired code signal a greater or less number of times, circuit controlling means operable by and during action of said mechanism to establish an interconnection between said paths, and means so governing such actuation of said circuit controlling means that said interconnection will be established only when action of said mechanism is uninterruptedly continued to and after the completion of a predetermined one or more formulations of said code signal; and a signal circuit comprising two parallel loops, said primary responsive device connected between one end of one of said loops and the opposite end of the other of said loops, said current source and said secondary responsive device connected between the remaining ends of said loops, and the two current paths of each station serially connected in respective ones of said loops.

21. In a signaling system: a primary responsive device; a current source; a secondary responsive device; signaling stations each having means for establishing two normally closed independent current paths therethrough, said means including mecha-

nism comprising contacts variably operable to break and close one of such paths to formulate a desired code signal, circuit controlling means operable by and during action 5 of said mechanism to establish an interconnection between said paths; and a signal circuit comprising two parallel loops, said primary responsive device connected between one end of one of said loops and the 10 opposite end of the other of said loops, said current source and said secondary responsive device connected between the remaining ends of said loops, and the two current paths of each station being so serially connected in respective ones of said 15 loops that the establishment of the described abnormal path at any station will interconnect the portions of said signal circuit which most directly connect such station and said current source.

22. In a signaling system: a primary responsive device; a current source; a secondary responsive device; signaling stations each having means for establishing two normally closed independent current paths therethrough, said means including code signaling mechanism comprising contacts variably operable to break and close one of such paths and circuit controlling means 25 operable by and during action of said mechanism to establish an abnormal current path comprising said contacts and parts of two normally independent current paths and to break one of said normally independent current paths in a part thereof which is not included in such abnormal path; and a signal circuit comprising two parallel loops, said primary responsive device connected between one end of one of said loops and the 30 opposite end of the other of said loops, said current source and said secondary responsive device connected between the remaining ends of said loops, and the two current paths of each station being so serially connected in respective ones of said loops that the establishment of the described abnormal path at any station will interconnect the portions of said signal circuit which most directly connect such station and said current source.

23. In a signaling system: a primary responsive device; a current source; a secondary responsive device; signaling stations each having code signaling mechanism comprising contacts variably operable to break and close one of two normally independent current paths and circuit controlling means operable by and during action of said mechanism to establish an abnormal current path comprising said contacts and parts of the two normally independent current paths to break the one of said normally independent current paths which is responsive to said code contacts in a part thereof which is not 55 included in such abnormal path; and a sig-

nal circuit comprising two parallel loops, said primary responsive device connected between one end of one of said loops and the opposite end of the other of said loops, said current source and said secondary responsive device connected between the remaining ends of said loops, and the two current paths of each station being so serially connected in respective ones of said loops that the establishment of the described abnormal path at any station will interconnect the portions of said signal circuit which most directly connect such station and said current source. 75

24. In a signaling system: a primary responsive device; a current source; a secondary responsive device; signaling stations each having code signaling mechanism comprising contacts variably operable to break and close one of two normally independent current paths and circuit controlling means operable by and during action of said mechanism to establish an abnormal current path comprising said contacts and parts of the two normally independent current paths and break both of said normally independent current paths in parts thereof which are not included in such abnormal current path; and a signal circuit comprising two parallel loops, said primary responsive device connected between one end of one of said loops and the opposite end of the other of said loops, said current source and said secondary responsive device connected between the remaining ends of said loops, and the two current paths of each station being so serially connected in respective ones of said loops that the establishment of the described abnormal path at any station will interconnect the portions of said signal circuit which most directly connect such station and said current source. 80 85 90 95 100

25. In a signaling system: a primary responsive device; a current source; a secondary responsive device; local responsive devices; signaling stations each comprising means for interconnecting two normally independent current paths through an associated one of said local responsive devices; and a signal circuit comprising two parallel loops, said primary responsive device connected between one end of one of said loops and the opposite end of the other of said loops, said current source and said secondary responsive device connected between the remaining ends of said loops, and said signaling stations serially connected in both of said loops. 105 110 115 120

26. In a signaling system: a primary responsive device; a current source; a secondary responsive device; local responsive devices; signaling stations each having code signaling mechanism comprising contacts variably operable to break and close one of two normally independent current paths 125 130

- either without or with an interconnection between such paths, which interconnection includes an associated one of said local responsive devices; and a signal circuit comprising 5 two parallel loops, said primary responsive device connected between one end of one of said loops and the opposite end of the other of said loops, said current source and said secondary responsive device connected 10 between the remaining ends of said loops, said signaling stations connected in both of said loops, and the two current paths of each station serially connected in respective ones of said loops.
- 15 27. In a signaling system: a primary responsive device; a current source; a secondary responsive device; local responsive devices; signaling stations each having code signaling mechanism comprising contacts 20 variably operable to break and close one of two normally independent current paths and means operable by and during the action of said mechanism to establish an interconnection between such paths, which interconnection 25 includes an associated one of said local responsive devices; and a signal circuit comprising two parallel loops, said primary responsive device connected between one end of one of said loops and the opposite end of the other of said loops, said current source and said secondary responsive device connected between 30 the remaining ends of said loops, and the two current paths of each station being so serially connected in respective ones of said loops that the code signaling contacts of each station will be included in the portion of one of the current paths thereof which is situated between the interconnection of such station and said current source.
- 35 28. In a signaling system: a primary responsive device; a current source; a secondary responsive device; signaling stations 40 each having mechanism comprising contacts variably operable to break and close one of two normally independent current paths to formulate a desired code signal a greater or less number of times, circuit controlling 45 means operable by and during action of said mechanism to establish an interconnection between said paths, and means so governing such actuation of said circuit controlling means that said interconnection will be est- 50ablished only when action of said mechanism is uninterrupted continued to and after the completion of a predetermined one or more formulations of said code signal; local responsive devices associated with re- 55 spective signaling stations and included in the interconnections thereof; and a signal circuit comprising two parallel loops, said primary responsive device connected be- 60 tween one end of one of said loops and the opposite end of the other of said loops, said current source and said secondary responsive device connected between the remaining ends of said loops, and the two current paths of each station serially connected in respec- 65 tive ones of said loops.

29. In a signaling system: a primary responsive device; a current source; a secondary responsive device; signaling stations each having mechanism comprising contacts 70 variably operable to break and close one of two normally independently current paths to formulate a desired code signal a greater or less number of times, circuit controlling means operable by and during action of said mechanism to establish an interconnection between said paths; local responsive devices associated with respective signaling stations and included in the interconnections thereof; and a signal circuit comprising two parallel loops, said primary responsive device connected between one end of one of said loops and the opposite end of the other of said loops, said current source and said secondary responsive device connected between 75 the remaining ends of said loops, and the two current paths of each station being so serially connected in respective ones of said loops that the code signaling contacts of each station will be included in the portion of one of the current paths thereof which is situated between the interconnection of such station and said current source.
- 80 30. In a signaling system: a primary responsive device; a current source; a secondary responsive device; signaling stations 85 each having code signaling mechanism comprising contacts variably operable to break and close one of two normally independent current paths and circuit controlling means operable by and during action of said mechanism to establish an abnormal current path comprising said contacts and parts of two normally independent current paths and to break one of said normally independent current paths in a part thereof which is not included in such abnormal path; local responsive devices associated with respective signaling stations and included in the abnormal current paths which may be established thereby; and a signal circuit comprising two parallel loops, said primary responsive device connected between one end of one of said loops and the opposite end of the other of said loops, said current source and said secondary responsive device connected between 90 the remaining ends of said loops, and the two current paths of each station being so serially connected in respective ones of said loops that the establishment of the described abnormal path at any station will 95 interconnect the portions of said signal circuit which most directly connect such station and said current source.
- 100 31. In a signaling system: a primary responsive device; a current source; a secondary responsive device; signaling stations 105 each having code signaling mechanism comprising contacts variably operable to break and close one of two normally independent current paths and circuit controlling means 110

- 115 120 125 130
- 115 120 125 130
- 115 120 125 130

- operable by and during action of said mechanism to establish an abnormal current path comprising said contacts and parts of the two normally independent current paths
- 5 to break the one of said normally independent current paths which is responsive to said code contacts in a part thereof which is not included in such abnormal path; local responsive devices associated with respective signaling stations and included in the abnormal current paths which may be established thereby; and a signal circuit comprising two parallel loops, said primary responsive device connected between one end
- 10 of one of said loops and the opposite end of the other of said loops, said current source and said secondary responsive device connected between the remaining ends of said loops, and the two current paths of each station being so serially connected in respective ones of said loops that the establishment of the described abnormal path at any station will interconnect the portions of said signal circuit which most directly connect such station
- 15 and said current source.
32. In a signaling system: a primary responsive device; a current source; a secondary responsive device; signaling stations each having code signaling mechanism comprising contacts variably operable to break and close one of two normally independent current paths and circuit controlling means operable by and during action of said mechanism to establish an abnormal current path comprising said contacts and parts of the two normally independent current paths and break both of said normally independent current paths in parts thereof which are not included in such abnormal current path;
- 20 local responsive devices associated with respective signaling stations and included in the abnormal current paths which may be established thereby; and a signal circuit comprising two parallel loops, said primary responsive device connected between one end of one of said loops and the opposite end of the other of said loops, said current source and said secondary responsive device connected between the remaining ends of said loops, and the two current paths of each station being so serially connected in respective ones of said loops that the establishment of the described abnormal path at any station will interconnect the portions of said signal circuit which most directly connect such station and said current source.
33. In a signaling system comprising a responsive device and a current source: a signal circuit in which said device is suitably connected, said circuit comprising two parallel loops, having a high resistance connection between one end of one of said loops and the opposite end of the other of said loops, and having the remaining ends of said loops connected to said current source; in combination with signaling stations each comprising two normally independent current paths therethrough, which paths are serially included in respective ones of the parallel loops of said circuit, a signaling train, contacts operable by and during each cycle of the running of said train to break and close one of said current paths to formulate a desired code signal, an electromagnet, means operated thereby for the initiation of the operative cycles of said train, means including said magnet and two circuit closers for establishing a branch current path between said two current paths, and means operating with said train for controlling one of said circuit closers so as to interrupt said branch path throughout each formulation of said code signal.
34. In a signaling system comprising a responsive device and a current source: a signal circuit in which said device is suitably connected, said circuit comprising two parallel loops, having a high resistance connection between one end of one of said loops and the opposite end of the other of said loops, and having said current source connected between the remaining ends of said loops; in combination with signaling stations each comprising two normally independent current paths therethrough, which paths are serially included in respective ones of the parallel loops of said circuit, a signaling train, contacts operable by and during each cycle of the running of said train to break and close one of said current paths to formulate a desired code signal, an electromagnet, means operated thereby for the initiation of the operative cycles of said train, circuit controlling mechanism for establishing a branch current path between said two current paths, means operating with said train for controlling said mechanism so as to interrupt said branch path throughout each formulation of said code signal, and means progressively operable by said train to shunt said circuit closer after a predetermined one or more operative cycles of said train.
35. In a signaling system comprising a responsive device and a current source: a signal circuit in which said device is suitably connected, said circuit comprising two parallel loops, having a high resistance connection between one end of one of said loops and the opposite end of the other of said loops, and having said current source connected between the remaining ends of said loops; in combination with signaling stations each comprising two normally independent current paths therethrough, which paths are serially included in respective ones of the parallel loops of said circuit, a signaling train, contacts operable by and during each cycle of the running of said train to break and close one of said current paths

to formulate a desired code signal, an electromagnet, means operated thereby for the initiation of the operative cycles of said train, circuit controlling mechanism for establishing a branch current path between said two current paths, means operating with said train for controlling said mechanism so as to interrupt said branch path throughout each formulation of said code signal, and means progressively operable by said train to shunt said circuit closer after a predetermined one or more operative cycles of said train, and to thereafter interrupt said branch path after a predetermined one or more additional operative cycles of said train.

36. In a signaling system: a current source; a signal circuit comprising two parallel loops, having a high resistance connection between one end of one of said loops and the opposite end of the other of said loops, and having said current source connected between the remaining ends of said loops; in combination with signaling stations each comprising two normally independent current paths therethrough, which paths are serially included in respective ones of the parallel loops of said circuit, a signaling train, contacts operable by and during each cycle of the running of said train to break and close one of said current paths to formulate a desired code signal, an electromagnet, means operated thereby for the initiation of the operative cycles of said train, means including said magnet and circuit controlling mechanism for establishing a branch current path between said two current paths, means operating with said train for controlling said mechanism so as to interrupt said branch path throughout each formulation of said code signal, and means progressively operable by said train to establish an interconnection between said normally independent current paths, which interconnection will connect with the one of said paths in which said path is connected; a primary device responsive to current flow in said signal circuit during ineffectiveness of the interconnections of all signaling stations; and a secondary device responsive to current flow from said source only during effectiveness of such an interconnection.

37. In a signaling system: a current source; a signal circuit comprising two parallel loops, having a high resistance connection between one end of one of said loops and the opposite end of the other of said loops, and having said current source connected between the remaining ends of said loops; in combination with signaling stations each comprising two normally inde-

pendent current paths therethrough, which paths are serially included in respective ones of the parallel loops of said circuit, a signaling train, contacts operable by and during each cycle of the running of said train to break and close one of said current paths to formulate a desired code signal, an electromagnet, means including said magnet and circuit controlling means for establishing a branch current path between said two current paths, means progressively operable by said train to establish an interconnection between said normally independent current paths, which interconnection will connect with the one of said paths which may be broken by said contacts in the portion thereof situated between such contacts and the high resistance connection of the one of the parallel loops in which said path is connected, and means operating with said train for controlling said circuit controlling means so as to interrupt said branch path throughout each formulation of said code signal and to render said interconnection effective during every closure of said code contacts; a primary device responsive to current flow in said signal circuit during ineffectiveness of the interconnections of all signaling stations; and a secondary device responsive to current flow from said source only during effectiveness of such an interconnection.

38. In a signaling system: a current source; a signal circuit comprising two parallel loops, having a high resistance connection between one end of one of said loops and the opposite end of the other of said loops, and having said current source connected between the remaining ends of said loops; in combination with signaling stations each comprising two normally independent current paths therethrough, which paths are serially included in respective ones of the parallel loops of said circuit, a signaling train, contacts operable by and during each cycle of the running of said train to break and close one of said current paths to formulate a desired code signal, an electromagnet, means operated thereby for the initiation of the operative cycles of said train, means including said magnet and circuit controlling mechanism for establishing a branch current path between said two current paths, means operating with said train for controlling said mechanism so as to interrupt said branch path throughout each formulation of said code signal, and means progressively operable by said train to shunt said circuit closer after a predetermined one or more operative cycles of said train and to establish an interconnection between said normally independent current paths, which interconnection will connect with the one of said paths which may be broken by said contacts in the portion there-

of situated between such contacts and the high resistance connection of the one of the parallel loops in which said path is connected; a primary device responsive to current flow in said signal circuit during ineffectiveness of the interconnections of all signaling stations; and a secondary device responsive to current flow from said source only during effectiveness of such an interconnection.

39. In a signaling train: a current source; a signal circuit comprising two parallel loops, having a high resistance connection between one end of one of said loops and the opposite end of the other of said loops, and having said current source connected between the remaining ends of said loops; in combination with signaling stations each comprising two normally independent current paths therethrough, which paths are serially included in respective ones of the parallel loops of said circuit, a signaling train, contacts operable by and during each cycle of the running of said train to break and close one of said current paths to formulate a desired code signal, an electromagnet, means operated thereby for the initiation of the operative cycles of said train, means including said magnet and two circuit controllers for establishing a branch current path between said two current paths, means progressively operable by said train to shunt said circuit closer after a predetermined one or more operative cycles of said train and to thereafter interrupt said branch path after a predetermined one or more additional operative cycles of said train, means operating with said train for controlling one of said circuit controllers so as to interrupt said branch path throughout each formulation of said code signal, to establish an interconnection between said normally independent current paths, which interconnection will connect with the one of said paths which may be broken by said contacts in the portion thereof situated between such contacts and the high resistance connection of the one of the parallel loops in which said path is connected, and to break said interconnection during each closure of said branch path thereby; a primary device responsive to current flow in said signal circuit during ineffectiveness of the interconnections of all signaling stations; and a secondary device responsive to current flow from said source only during effectiveness of such an interconnection.

40. In a signaling system: a current source; a signal circuit comprising two parallel loops, having a high resistance connection between one end of one of said loops and the opposite end of the other of said loops, and having said current source connected between the remaining ends of said loops; in combina-

tion with signaling stations each comprising two normally independent current paths therethrough, which paths are serially included in respective ones of the parallel loops of said circuit, a signaling train, contacts operable by and during each cycle of the running of said train to break and close one of said current paths to formulate a desired code signal, an electromagnet, means operated thereby for the initiation of the operative cycles of said train, means including said magnet and two circuit closers for establishing a branch current path between said two current paths, means progressively operable by said train to shunt one of said circuit closers after a predetermined one or more operative cycles of said train and to establish an interconnection between said normally independent current paths, which interconnection will connect with the one of said paths which may be broken by said contacts in the portion thereof situated between such contacts and the high resistance connection of the one of the parallel loops in which said path is connected, and means operating with said train for controlling one of said circuit closers so as to interrupt said branch path throughout each formulation of said code signal and to close the interruption produced thereby in said path at the initiation of each of such operative cycles, to render said interconnection effective during every closure of said code contacts and to break said interconnection during each closure of said branch path thereby; a primary device responsive to current flow in said signal circuit during ineffectiveness of the interconnections of all signaling stations; and a secondary device responsive to current flow from said source only during effectiveness of such an interconnection.

41. In a signaling system: a current source; a signal circuit comprising two parallel loops, having a high resistance connection between one end of one of said loops and the opposite end of the other of said loops, and having said current source connected between the remaining ends of said loops; in combination with signaling stations each comprising two normally independent current paths therethrough, which paths are serially included in respective ones of the parallel loops of said circuit, a signaling train, contacts operable by and during each cycle of the running of said train to break and close one of said current paths to formulate a desired code signal, an electromagnet, means operated thereby for the initiation of the operative cycles of said train, means including said magnet and two circuit closers for establishing a branch current path between said two current paths, means progressively operating with said train for controlling suitable ones of said circuit closers so as to shunt the aforesaid

one thereof after a predetermined one or more operative cycles of said train, so as to establish an interconnection between said normally independent current paths, which 5 interconnection will connect with the one of said paths which may be broken by said contacts in the portion thereof situated between such contacts and the high resistance connection of the one of the parallel loops in 10 which said path is connected, so as to thereafter interrupt said branch path after a predetermined one or more additional operative cycles of said train, and so as to interrupt said branch path throughout each formulation 15 of said code signal and to close the interruption produced thereby in said path at the initiation of each of such operative cycles, so as to render said interconnection effective during every closure of said code 20 contacts and so as to break said interconnection during each closure of said branch path thereby; a primary device responsive to current flow in said signal circuit during ineffectiveness of the interconnections of all 25 signaling stations; and a secondary device responsive to current flow from said source only during effectiveness of such an interconnection.

42. A signaling circuit comprising two 30 parallel loops: a comparatively high resistance connection between one end of one of said loops and the opposite end of the other of said loops: a current source connected between the remaining ends of said 35 loops: responsive devices suitably connected in said loops: and signaling stations each included in both of said loops and each having;—a circuit closer, one terminal of which is connected to one of said loops; a signaling train; a detent for said train; an electromagnet for operating said detent; mechanical holding means moved by said train to retain said detent in operated position during a predetermined part of each 40 cycle of the running thereof; a branch current path including said magnet, said branch path extending from the remaining terminal of said circuit closer to the other of said loops; and code signaling means 45 actuated by said train in running to interrupt and establish current flow in said loops during the retaining action of said mechanical holding means incident to each cycle of the running of said train.

43. A signaling circuit comprising two 50 parallel loops; a comparatively higher resistance connection between one end of one of said loops and the opposite end of the other of said loops: a current source connected between the remaining ends of said 55 loops: responsive device suitably connected in said loops: and signaling stations each included in both of said loops and each having;—a circuit closer, one terminal of which is connected to one of said loops;

a signaling train; a detent for said train; an electromagnet for operating said detent; mechanical holding means moved by said train to retain said detent in operated position during a predetermined part of each 60 cycle of the running thereof; a branch current path including said magnet, said branch path extending from the remaining terminal of said circuit closer to the other of said loops; and code signaling means actuated by said train in running to interrupt and establish current flow in said loops during the retaining action of said mechanical holding means incident to each cycle of the running of said train.

44. A signaling circuit comprising two 65 parallel loops: a comparatively high resistance connection between one end of one of said loops and the opposite end of the other of said loops: a current source connected between the remaining ends of said loops: responsive devices suitably connected in said loops: and signaling stations each included in both of said loops and each having;—a circuit closer, one terminal of which is connected to one of said loops; a signaling train; a detent for said train; an electromagnet for operating said detent; mechanical holding means moved by said train to retain said detent in operated position during a predetermined part of each 70 cycle of the running thereof; a branch current path including said magnet, said branch path extending from the remaining terminal of said circuit closer to the other of said loops; and code signaling means actuated by said train in running to interrupt and establish current flow in said loops during the retaining action of said mechanical holding means incident to each cycle of the running of said train; and circuit controlling means progressively operable by said train to interrupt said branch path after said train has accomplished said cycle a predetermined one or more times.

45. In a signaling system: a current source; a plurality of signaling stations; a current path from one terminal of said source, through said stations in the desired sequence; a current path from the other terminal of said source, through said stations in reverse sequence; a connection of comparatively high resistance between the remaining ends of said paths; a responsive device included in one of said current paths between the current source and said stations; and mechanism at each of said stations com-

prising a normally wound train, formulating means operable by said train for interrupting and establishing current flow in said paths in conformity with a predetermined code, an electromagnet, a detent for said train operable by said magnet, means adjustable for establishing a connection including said magnet between said current paths, and mechanical holding means so moved by the running of said train as to retain said detent in operated position throughout the interruptions in current flow incident to the actuation of said formulating means.

46. In a signaling system:—a signal circuit comprising two parallel loops: a connection of comparatively high resistance between one end of one of said loops and the opposite end of the other of said loops: a current source connected between the remaining ends of said loops: signaling stations each included in both of said loops and each comprising;—a signaling train comprising means for formulating a code signal; contacts operable by said formulating means to break and make one of said loops; and electromagnet for controlling said train; releasing means operable by said magnet to start said train, said releasing means being arranged to cause said train to act to formulate a greater or less number of cycles of said code signal as determined by the effectiveness of said magnet after each of such cycles; a branch current path including said magnet, one end of said branch path being connected to one of said loops; a normally ineffective interconnection between said loops positioned to provide a current path from said source, including said contacts, and adapted to shunt portions of said loops extending to said high resistance connection; circuit controlling means periodically actuated by said train in running for breaking said branch path during all of the circuit breaks incident to each of said formulating cycles; and circuit controlling means progressively operated by said train so as to connect the remaining end of said branch path to the other of said loops after said train has accomplished said formulating cycle a predetermined one or more times and for thereafter interrupting said branch path after said train has accomplished said cycle a predetermined additional one or more times, said progressively operated means being further arranged to break the shunted portion of one of said loops after said train has accomplished said cycle a predetermined one or more times, said progressively operated means and said periodically operated means being arranged to cooperate to render said interconnection effective, during every closure of said formulating contacts, after said train has accomplished said cycle a predetermined one or more times, and to break

said interconnection during each closure of said branch path: a secondary device responsive only to current flow not less than such as occurs during the effectiveness of any such interconnections: and a primary device responsive to such current flow as that through said high resistance connection during the ineffectiveness of said interconnections; said devices being suitably connected in said loops. 75

47. In a signaling system:—a signal circuit comprising two parallel loops: a connection of comparatively high resistance between one end of one of said loops and the opposite end of the other of said loops: a current source connected between the remaining ends of said loops: signaling stations each included in both of said loops and each comprising;—a signaling train comprising means for formulating a code signal; contacts operable by said formulating means to break and make one of said loops; an electromagnet for controlling said train; releasing means operable by said magnet to start said train, said releasing means being arranged to cause said train to act to formulate a greater or less number of cycles of said code signal as determined by the effectiveness of said magnet after each of such cycles; a branch current path including said magnet, one end of said branch path being connected to one of said loops; a normally ineffective interconnection between said loops positioned to provide a current path from said source, including said contacts, and adapted to shunt portions of said loops extending to said high resistance connection; circuit controlling means periodically actuated by said train in running for breaking said branch path during all of the circuit breaks incident to each of said formulating cycles; and circuit controlling means progressively operated by said train so as to connect the remaining end of said branch path to the other of said loops after said train has accomplished said formulating cycle a predetermined one or more times, and for thereafter interrupting said branch path after said train has accomplished said cycle a predetermined additional one or more times, said progressively operated means and said periodically operated means being arranged to co-operate to render said interconnection effective, during every closure of said formulating contacts, after said train has accomplished said cycle a predetermined one or more times, and to break said interconnection during each closure of said branch path: a secondary device responsive only to current flow not less than such as occurs during the effectiveness of any of such interconnections: and a primary device responsive to such current flow as that through said high resistance connection during the ineffectiveness of said interconnections; said 120

devices being suitably connected in said loops.

48. In a signaling system:—a signal circuit comprising two parallel loops: a connection of comparatively high resistance between one end of one of said loops and the opposite end of the other of said loops: a current source connected between the remaining ends of said loops: signaling stations each included in both of said loops and each comprising;—a signaling train comprising means for formulating a code signal; contacts operable by said formulating means to break and make one of said loops; an electromagnet for controlling said train; releasing means operable by said magnet to start said train, said releasing means being arranged to cause said train to act to formulate a greater or less number of cycles of said code signal as determined by the effectiveness of said magnet after each of such cycles; a branch current path including said magnet, one end of said branch path being connected to one of said loops; a normally ineffective interconnection between said loops positioned to provide a current path from said source, including said contacts, and adapted to shunt portions of said loops extending to said high resistance connection; circuit controlling means periodically actuated by said train in running for breaking said branch path during all of the circuit breaks incident to each of said formulating cycles; and circuit controlling means progressively operated by said train so as to connect the remaining end of said branch path to the other of said loops after said train has accomplished said formulating cycle a predetermined one or more times, and for thereafter interrupting said branch path after said train has accomplished said cycle a predetermined additional one or more times, said progressively operated means and said periodically operated means being arranged to co-operate to render said interconnection effective, during every closure of said formulating contacts, after said train has accomplished said cycle a predetermined one or more times, and to break said interconnection during each closure of said branch path: a secondary device responsive only to current flow not less than such as occurs during the effectiveness of any of such interconnections: and a primary device responsive to such current flow as that through said high resistance connection during the ineffectiveness of said interconnection; said devices being suitably connected in said loops: and local responsive devices connected in the interconnections of respective signaling stations.

49. In a signaling system:—a signal circuit comprising two parallel loops: a connection of comparatively high resistance between one end of one of said loops and the

opposite end of the other of said loops: a current source connected between the remaining ends of said loops: signaling stations each included in both of said loops and each comprising;—a signaling train comprising means for formulating a code signal; contacts operable by said formulating means to break and make one of said loops; an electromagnet for controlling said train; releasing means operable by said magnet to start said train, said releasing means being arranged to cause said train to act to formulate a greater or less number of cycles of said code signal as determined by the effectiveness of said magnet after each of such cycles; a branch current path including said magnet, one end of said branch path being connected to one of said loops; a normally ineffective interconnection between said loops positioned to provide a current path from said source, including said contacts, and adapted to shunt portions of said loops extending to said high resistance connection; circuit controlling means periodically actuated by said train in running for breaking said branch path during all of the circuit breaks incident to each of said formulating cycles; and circuit controlling means progressively operated by said train so as to connect the remaining end of said branch path to the other of said loops after said train has accomplished said formulating cycle a predetermined one or more times, and for thereafter interrupting said branch path after said train has accomplished said cycle a predetermined additional one or more times, said progressively operated means being further arranged to break the shunted portion of the one of said loops which includes said formulating contacts after said train has accomplished said cycle a predetermined one or more times, said periodically operated means being arranged to render said interconnection effective during every closure of said formulating contacts and to break said interconnection during each closure of said branch path: a secondary device responsive only to current flow not less than such as occurs during the effectiveness of any of such interconnections: and a primary device responsive to such current flow as that through said high resistance connection during the ineffectiveness of said interconnections; said devices being suitably connected in said loops.

50. In a signaling system:—a signal circuit comprising two parallel loops: a connection of comparatively high resistance between one end of one of said loops and the opposite end of the other of said loops: a current source connected between the remaining ends of said loops: signaling stations each included in both of said loops and each comprising;—a signaling train com-

- prising means for formulating a code signal; contacts operable by said formulating means to break and make one of said loops; an electromagnet for controlling said train; 5 releasing means operable by said magnet to start said train, said releasing means being arranged to cause said train to act to formulate a greater or less number of cycles of said code signal as determined by the effectiveness of said magnet after each of such cycles; a branch current path including said magnet, one end of said branch path being connected to one of said loops; a normally ineffective interconnection between said 10 loops positioned to provide a current path from said source, including said contacts, and adapted to shunt portions of said loops extending to said high resistance connection; circuit controlling means periodically actuated by said train in running for breaking said branch path during all of the circuit breaks incident to each of said formulating cycles; and circuit controlling means periodically actuated by said train in running for breaking said branch path during all of the circuit breaks incident to each of said formulating cycles; and circuit controlling means progressively operated by said train so as to 15 connect the remaining end of said branch path to the other of said loops after said train has accomplished said formulating cycle a predetermined one or more times, and for thereafter interrupting said branch path 20 after said train has accomplished said cycle a predetermined additional one or more times, said progressively operated means being further arranged to break the shunted portion of the one of said loops which 25 includes said formulating contacts after said train has accomplished said cycle a predetermined one or more times, said progressively operated means and said periodically operated means being arranged to cooperate 30 to render said interconnection effective, during every closure of said formulating contacts, after said train has accomplished said cycle a predetermined one or more times, and to break said interconnection during 35 each closure of said branch path: a secondary device responsive only to current flow not less than such as occurs during the effectiveness of any of such interconnections: and a primary device responsive to such current flow as that through said high resistance connection during the ineffectiveness of said interconnections; said devices being 40 suitably connected in said loops.
52. In a signaling system:—a signal circuit comprising two parallel loops: a connection of comparatively high resistance between one end of one of said loops and the opposite end of the other of said loops: a current source connected between the remaining ends of said loops: signaling stations each included in both of said loops and each comprising;—a signaling train comprising means for formulating a code signal; contacts operable by said formulating means to break and make one of said loops; an electromagnet for controlling said train; releasing means operable by said magnet to start said train, said releasing means being arranged to cause said train to act to formulate a greater or less number of cycles of said code signal as determined by the effectiveness of said magnet after 45 50 55 60 65 70 75 80 85 90 95 100 105 110 115 120 125 130
51. In a signaling system:—a signal circuit comprising two parallel loops: a connection of comparatively high resistance between one end of one of said loops and the opposite end of the other of said loops: a current source connected between the remaining ends of said loops: signaling stations each included in both of said loops and each comprising;—a signaling train comprising means for formulating a code signal; contacts operable by said formulating means to break and make one of said loops; an electromagnet for controlling said train; releasing means operable by said magnet to start said train, said releasing means being arranged to cause said train to act to formulate a greater or less number of cycles of said code signal as determined by the effectiveness of said magnet after 55 60 65 70 75 80 85 90 95 100 105 110 115 120 125 130

each of such cycles; a branch current path including said magnet, one end of said branch path being connected to one of said loops; a normally ineffective interconnection between said loops positioned to provide a current path from said source, including said contacts, and adapted to shunt portions of said loops extending to said high resistance connection; circuit controlling means periodically actuated by said train in running for breaking said branch path during all of the circuit breaks incident to each of said formulating cycles; and circuit controlling means progressively 70 operated by said train so as to connect the remaining end of said branch path to the other of said loops after said train has accomplished said formulating cycle a predetermined one or more times, and for there- 75 after interrupting said branch path after said train has accomplished said cycle a predetermined additional one or more times, said progressively operated means being further arranged to break the shunted por- 80 tions of both of said loops after said train has accomplished said cycle a predetermined one or more times, said progressively operated means and said periodically operated means being arranged to co-operate 85 25 90 30 95 35 100 40 105 45 110 50 115 55 120 60 125 65 130

interconnection between said loops positioned to provide a current path from said source, including said contacts, and adapted to shunt portions of said loops extending to said high resistance connection; circuit controlling means periodically actuated by said train in running for breaking said branch path during all of the circuit breaks incident to each of said formulating cycles; and circuit controlling means progressively operated by said train so as to connect the remaining end of said branch path to the other of said loops after said train has accomplished said formulating cycle a predetermined one or more times, and for there- after interrupting said branch path after said train has accomplished said cycle a predetermined additional one or more times, said progressively operated means being further arranged to break the shunted portions of both of said loops after said train has accomplished said cycle a predetermined one or more times, said progressively operated means being arranged to render said interconnection effective during every closure of said formulating contacts and to break said interconnection during each closure of said branch path: a secondary device responsive only to current flow not less than such as occurs during the effectiveness of any of such interconnections: a primary device responsive to such current flow as that through said high resistance connection during the ineffectiveness of said interconnections; said devices being suitably connected in said loops: and local responsive devices connected in the interconnections of respective signaling stations.

53. In a signaling system:—a signal circuit comprising two parallel loops: a connection of comparatively high resistance between one end of one of said loops and the other of said loops; a current source connected between the remaining ends of said loops: signaling stations each included in both of said loops and each comprising;—a signaling train comprising means for formulating a code signal; contacts operable by said formulating means to break and make one of said loops; an electromagnet for controlling said train; releasing means operable by said magnet to start said train, said releasing means being arranged to cause said train to act to formulate a greater or less number of cycles of said code signal as determined by the effectiveness of said magnet after each of such cycles; a branch current path including said magnet, one end of said branch path being connected to one of said loops; a normally ineffective interconnection between said loops positioned to provide a current path from said source, including said contacts, and adapted to shunt portions of said loops extending to said high resistance connec-

54. In a signaling system:—a signal circuit comprising two parallel loops: a connection of comparatively high resistance between one end of one of said loops and the opposite end of the other of said loops: a current source connected between the remaining ends of said loops: signaling stations each included in both of said loops and each comprising;—a signaling train comprising means for formulating a code signal; contacts operable by said formulating means to break and make one of said loops; an electromagnet for controlling said train; releasing means operable by said magnet to start said train, said releasing means being arranged to cause said train to act to formulate a greater or less number of cycles of said code signal as determined by the effectiveness of said magnet after each of such cycles; a branch current path including said magnet, one end of said branch path being connected to one of said loops; a normally ineffective interconnection between said loops positioned to provide a current path from said source, including said contacts, and adapted to shunt portions of said loops extending to said high resistance connec-

- tion; circuit controlling means periodically actuated by said train in running for breaking said branch path during all of the circuit breaks incident to each of said formulating cycles; and circuit controlling means progressively operated by said train so as to connect the remaining end of said branch path to the other of said loops after said train has accomplished said formulating 5 cycle a predetermined one or more times, and for thereafter interrupting said branch path after said train has accomplished said cycle a predetermined additional one or more times, said progressively operated 10 means being further arranged to break the shunted portions of both of said loops after said train has accomplished said cycle a predetermined one or more times, said progressively operated means and said periodically operated means being arranged to co-operate to render said interconnection effective, during every closure of said formulating contacts, after said train has accomplished said cycle a predetermined one or 15 more times, and to break said interconnection during each closure of said branch path: a secondary device responsive only to current flow not less than such as occurs during the effectiveness of any of such interconnections: a primary device responsive to such current flow as that through said high resistance connection during the ineffectiveness of said interconnections; said devices being suitably connected in said loops: and 20 local responsive devices connected in the interconnections of respective signaling stations.
55. In a signaling system:—a signal circuit comprising two parallel loops, one end 40 of one of said loops being connected to the opposite end of the other of said loops: a responsive device suitably connected in one of said loops: a current source connected between the remaining ends of said loops: signaling stations each included in both of said loops and each comprising;—a signaling train comprising means for formulating a code signal; contacts operable by said formulating means to break and make one 45 of said loops; an electromagnet for controlling said train, said magnet being so connected and arranged with reference to one of said loops as to be adapted for effective energization thereof from said signal circuit; releasing means operable by said magnet to start said train, said releasing means being arranged to cause said train to act to 50 formulate a greater or less number of cycles of said code signal as determined by the effectiveness of said magnet after each of such cycles; a normally ineffective interconnection between said loops positioned to provide a current path from said source, including said contacts, and adapted to shunt the connected portions of said loops; circuit controlling means periodically actuated by said train in running for rendering said interconnection effective during each of the circuit breaks incident to each of said formulating cycles; circuit controlling means periodically actuated by said train in running for rendering said interconnection effective during each of the circuit breaks incident to each of said formulating cycles; and circuit controlling 55 means progressively operated by said train for causing effective energization of said magnet after said train has accomplished said formulating cycle a predetermined one or more times, and for thereafter preventing effective energization of said magnet after said train has accomplished said cycle a predetermined additional one or more times.
56. In a signaling system:—a signal circuit comprising two parallel loops, one end 60 of one of said loops being connected to the opposite end of the other of said loops: a responsive device suitably connected in one of said loops: a current source connected between the remaining ends of said loops: signaling stations each included in both of said loops and each comprising;—a signaling train comprising means for formulating a code signal; contacts operable by said formulating means to break and make one of said loops; an electromagnet for controlling said train, said magnet being connected in one of said loops; releasing means operable by said magnet to start said train, said releasing means being arranged to cause said train to act to formulate a greater or less number of cycles of said code signal as determined by the effectiveness of said magnet after each of such cycles; a normally ineffective interconnection between said loops positioned to provide a current path from said source, including said contacts, and adapted to shunt the connected portions of said loops; circuit controlling means periodically actuated by said train in running for rendering said interconnection effective during each of the circuit breaks incident to each of said formulating cycles; circuit controlling means progressively operated by said train for causing effective energization of said magnet after said train has accomplished said formulating cycle a predetermined one or more times, and for thereafter preventing effective energization of said magnet after said train has accomplished said cycle a predetermined additional one or more times, said progressively operated means being further arranged to break the shunted portion of the one of said loops which includes said formulating contacts after said train has accomplished said cycle a predetermined one or more times: and local responsive devices connected in the interconnections of respective signaling stations.
57. In a signaling system: a current source; a plurality of signaling stations; primary and secondary responsive devices; a current path from one terminal of said source, through said stations in the desired 100 105 110 115 120 125 130

- sequence, to one terminal of said primary responsive device; a current path from the other terminal of said source, through said stations in reverse sequence, to the other terminal of said primary device, said secondary device being included in one of said current paths between the current source and said stations; and mechanism at each of said stations comprising a normally wound train, tripping means therefor including a magnet means adjustable for establishing a connection including said magnet between said current paths, and formulating means operable by said train for 10 breaking and closing one of said paths in conformity with a predetermined code and for rendering said magnet connection ineffective during such breaks.
58. In a signaling system: a current source; a plurality of signaling stations; primary and secondary responsive devices; a current path from one terminal of said source, through said stations in the desired sequence, to one terminal of said primary responsive device; a current path from the other terminal of said source, through said stations in reverse sequence, to the other terminal of said primary device, said secondary device being included in one of said current paths between the current source and said stations; and mechanism at each of said stations comprising a normally wound train, formulating means operable by said train for interrupting and establishing current flow in said paths in conformity with a predetermined code, an electromagnet, a 20 detent for said train operable by said magnet, means adjustable for establishing a connection including said magnet between said current paths, and mechanical holding means so moved by the running of said train as to retain said detent in operated position throughout the interruptions in current flow incident to the actuation of said formulating means.
59. In a signaling system: a current source; a plurality of signaling stations; primary and secondary responsive devices; a current path from one terminal of said source, through said stations in the desired sequence, to one terminal of said primary responsive device; a current path from the other terminal of said source, through said stations in reverse sequence, to the other terminal of said primary device, said secondary device being included in one of said current paths between the current source and said stations; and mechanism at each of said stations comprising a normally wound train, 30 formulating means operable by said train for breaking and closing one of said paths in conformity with a predetermined code, an electromagnet, a detent for said train operable by said magnet, means adjustable for establishing a connection including said magnet between said current paths, and mechanical holding means so moved by the running of said train as to retain said detent in operated position throughout the interruptions in current flow incident to the actuation of said formulating means.
60. In a signal transmitter: a signaling train comprising means for formulating a 40 code signal including normally closed signaling contacts; two current paths each normally closed and isolated from the other, and one of which paths serially includes said contacts; releasing means operable to start said train; and an electromagnet for controlling said releasing means and having one end of the winding thereof connected to one of said current paths and the other end of said winding arranged for connection of an extraneous current path thereto independently of said first named two paths.
61. In a signal transmitter,—a signaling train, a detent therefor, an electromagnet for operating said detent, two normally closed independent current paths, one of which includes said electromagnet, means actuated by said train in running to break and make the other of said paths to formulate a desired code signal therein and to break said magnet path throughout each such formulation and to thereupon close said path, and a member moved by said train in running for rendering said detent ineffective throughout each of such breaks of said magnet path.
62. In a signal transmitter: a signaling train comprising means for formulating a code signal; an electromagnet for controlling said train; releasing means operable by said magnet to start said train and involving means arranged to cause said train to act to formulate a greater or less number of cycles of said code signal as determined by the effectiveness of said magnet after each of such cycles; two normally closed independent current paths; contacts operable by said formulating means to break and make one of said paths; a branch current path including said magnet, one end of said branch path being connected to one of said independent paths; and circuit controlling means operable by said train in running for breaking said branch path throughout each of said formulating cycles.
63. In a signal transmitter: a signaling train comprising means for formulating a code signal; an electromagnet for controlling said train; releasing means operable by said magnet to start said train and involving means arranged to cause said train to act to formulate a greater or less number of cycles of said code signal as determined by the effectiveness of said magnet after each of such cycles; two normally closed independent current paths; contacts operable by said

- formulating means to break and make one of said paths; a branch current path including said magnet, one end of said branch path being connected to one of said independent paths; and circuit controlling means operable by said train in running for breaking said branch path throughout each of said formulating cycles, and for connecting the remaining end of said branch path to the other of said independent paths after said train has accomplished said formulating cycle a predetermined one or more times. 64. In a signal transmitter:—a signaling train; a detent therefor; an electromagnet for operating said detent; two normally closed independent current paths and a branch current path including said magnet, one end of said branch current path being connected to one of said independent current paths; means actuated by said train in running to break and make the other of said independent current paths to formulate a desired code signal therein and to break said branch current path throughout such formulation; a member moved by said train in running for rendering said detent ineffective throughout each of such breaks of said branch current path; and means operable by said train in running to connect the other end of said branch current path to the remaining one of said independent current paths after said train has acted to formulate such code signal a predetermined one or more times. 65. In a signal transmitter: a signaling train comprising means for formulating a code signal; an electromagnet for controlling said train; releasing means operable by said magnet to start said train and involving means arranged to cause said train to act to formulate a greater or less number of cycles of said code signal as determined by the effectiveness of said magnet after each of such cycles; two normally closed independent current paths; contacts operable by said formulating means to break and make one of said paths; a branch current path including said magnet, one end of said branch path being connected to one of said independent paths; and circuit controlling means operable by said train in running for breaking said branch path throughout each of said formulating cycles, for connecting the remaining end of said branch path to the other of said independent paths after said train has accomplished said formulating cycle a predetermined one or more times, and for thereafter interrupting said branch path after said train has accomplished said formulating cycle a predetermined additional one or more times. 66. In a signal transmitter: a signaling train comprising means for formulating a code signal; an electromagnet for controlling said train; releasing means operable by said magnet to start said train and involving means arranged to cause said train to act to formulate a greater or less number of cycles of said code signal as determined by the effectiveness of said magnet after each of such cycles; two normally closed independent current paths; contacts operable by said formulating means to break and make one of said paths; a branch current path including said magnet, one end of said branch path being connected to one of said independent paths; and circuit controlling means operable by said train in running for breaking said branch path throughout each of said formulating cycles, for connecting the remaining end of said branch path to the other of said independent paths after said train has uninterruptededly accomplished said formulating cycle a predetermined one or more times, and for thereafter interrupting said branch path after said train has accomplished said formulating cycle a predetermined additional one or more times, said controlling means being unresponsive to interruption of the running of said train after accomplishment of such cycle thereby such additional times. 67. In a signal transmitter: a signaling train comprising means for formulating a code signal; an electromagnet for controlling said train; releasing means operable by said magnet to start said train and involving means arranged to cause said train to act to formulate a greater or less number of cycles of said code signal as determined by the effectiveness of said magnet after each of such cycles; two normally closed independent current paths; contacts operable by said formulating means to break and make one of said paths; a branch current path including said magnet, one end of said branch path being connected to one of said independent paths; circuit controlling means operable by said train in running for breaking said branch path throughout each of said formulating cycles, for connecting the remaining end of said branch path to the other of said independent paths after said train has accomplished said formulating cycle a predetermined one or more times, and for thereafter interrupting said branch path after said train has accomplished said formulating cycle a predetermined additional one or more times; and manually operable means for restoring said controlling means to normal condition after having been operated by said train such additional times. 68. In a signal transmitter:—a signaling train comprising means for formulating a code signal; releasing means operable for causing said train to act to formulate said code signal a greater or less number of times; two normally closed independent current paths; contacts operable by said

formulating means to break and make one of said paths; and means operable by said train in running, after said train has acted to formulate said code signal a predetermined one or more times, to break one of said paths and to interconnect an end of such broken path and the other of said paths.

69. In a signal transmitter:—a signaling train comprising means for formulating a code signal; releasing means operable for causing said train to act to formulate said code signal a greater or less number of times; two normally closed independent current paths; contacts operable by said formulating means to break and make one of said paths; and means operable by said train in running, after said train has acted to formulate said code signal a predetermined one or more times, to break the one of said paths which includes said contacts and to close a revised path of which the end of such broken path which includes said contacts will form part.

70. In a signal transmitter:—a signaling train comprising means for formulating a code signal; releasing means operable for causing said train to act to formulate said code signal a greater or less number of times; two normally closed independent current paths; circuit breaking and making contacts included in one of said paths and operable by said formulating means; and means operable by said train in running, after said train has acted to formulate said code signal a predetermined one or more times, to break the one of said paths which includes said contacts and to interconnect an end of such broken path and the other of said paths.

71. In a signal transmitter: a signaling train comprising means for formulating a code signal; an electromagnet for controlling said train; releasing means operable by said magnet to start said train and involving means arranged to cause said train to act to formulate a greater or less number of cycles of said code signal as determined by the effectiveness of said magnet after each of such cycles; two normally closed independent current paths; contacts operable by said formulating means to break and make one of said paths; a branch current path including said magnet, one end of said branch path being connected to one of said independent paths; circuit controlling means operable by said train in running for breaking said branch path throughout each of said formulating cycles, for connecting the remaining end of said branch path to the other of said independent paths and for breaking one of said independent paths after said train has accomplished said formulating cycle a predetermined one or more times, and for thereafter interrupting said

branch path after said train has accomplished said formulating cycle a predetermined additional one or more times; and manually operable means for restoring said controlling means to normal condition after having been operated by said train such additional times.

72. In a signal transmitter: a signaling train comprising means for formulating a code signal; an electromagnet for controlling said train; releasing means operable by said magnet to start said train and involving means arranged to cause said train to act to formulate a greater or less number of cycles of said code signal as determined by the effectiveness of said magnet after each of such cycles; two normally closed independent current paths; contacts operable by said formulating means to break and make one of said paths; a branch current path including said magnet, one end of said branch path being connected to one of said independent paths; circuit controlling means operable by said train in running for breaking said branch path throughout each of said formulating cycles for breaking both of said independent paths and for connecting the remaining end of said branch path to a broken end of one of said independent paths after said train has accomplished said formulating cycle a predetermined one or more times, and for thereafter interrupting said branch path after said train has accomplished said formulating cycle a predetermined additional one or more times; and manually operable means for restoring said controlling means to normal condition after having been operated by said train such additional times.

73. In a signal transmitter: a signaling train; contacts variably operable by said train to transmit a predetermined code signal a greater or less number of times; normally open contacts closed by said train in running throughout certain repetitions of said code signal; three pairs of circuit terminals; and conductors serially connecting said code contacts between one and the other of the terminals of one of said pairs so as to provide a normally closed current path therebetween, providing a current path between one and the other of the terminals of a second pair, and providing branch current paths between the terminals of the third pair and respective ones of said first named two paths, one of which branch paths serially includes said normally open contacts.

74. In a signal transmitter: a signaling train; contacts variably operable by said train to transmit a predetermined code signal a greater or less number of times; circuit controlling mechanism operable by said train in running to break one current path and establish another throughout certain repetitions of said code signal; three pairs

of circuit terminals; and conductors so interconnecting said terminals, said code contacts and said circuit controlling mechanism as to provide normally closed independent current paths between the respective terminals of two of said pairs, one of which paths serially includes said code contacts and one of which paths may be broken by said circuit controlling mechanism, together with branch current paths between the terminals of the third pair and respective ones of said first named two paths, one of which branch paths is normally interrupted by said circuit controlling mechanism.

75. In a signal transmitter; a signaling train having a recurrent cycle of action, releasing means operable for permitting said train to accomplish said cycle a greater or less number of times, an electromagnet for operating said releasing means, two current paths one of which paths includes said magnet, and means operable by said train in running to interconnect said paths throughout certain of said cycles.

76. In a signal transmitter; a signaling train having a recurrent cycle of action, re-

leasing means operable for permitting said train to accomplish said cycle a greater or less number of times, an electromagnet for operating said releasing means two current paths one of which is suitably connected to said magnet, and interconnecting means for said paths rendered effective by said train in running after a predetermined one or more of the operative cycles thereof.

77. In a signal transmitter; a signaling train having a recurrent cycle of action, releasing means operable for permitting said train to accomplish said cycle a greater or less number of times, an electromagnet for operating said releasing means, two current paths one of which is suitably connected to said magnet, and circuit controlling means operable by said train in running to interconnect said paths throughout certain of said cycles and to prevent further energization of said magnet following the conclusion of such cycles.

In witness whereof, I hereunto subscribe my name, this 24th day of November, 1920. 50

CLARENCE E. BEACH.
